HEEL END ASSEMBLING AND BREAST LINE LASTING MACHINES

Edward Quinn, Peabody, and William D. McKeon, Beverly, Mass., assignors to United Shoe Machinery Corporation, Flemington, N.J., a corporation of New Jersey

Filed Jan. 6, 1958, Ser. No. 707,299

49 Claims. (Cl. 12—1)

This invention relates to machines for operating on the heel end portions of shoes and is herein illustrated in its application to machines for inserting heel stiffeners or counters into shoe uppers, shaping the assembled parts, and attaching them to insoles.

United States Letters Patent No. 2,740,138, granted April 3, 1956, on an application filed in the name of Edward Quinn, discloses a machine for inserting counters into shoe uppers and shaping the assembled parts on their lasts. Machines of this type require the sorting of counters according to size and the handling of individual counters preparatory to each operation of the machine. Machines of this type also require the handling of a shoe last for each operation of the machine. In the Quinn machine the machine cycle is interrupted at a predetermined point to permit the operator to insert the last into the supported upper and to advance the last heelwardly into the heel end of the upper.

In general, it is the object of the present invention to facilitate and expedite the operation of machines of this type and to effect economies in their construction and maintenance.

More specifically it is an object of the present invention to eliminate the sorting of counters at the counter inserting operation and the handling of individual counters preparatory to the operation of the machine. It is a further object of the invention to eliminate the handling of lasts in connection with the operation of the machine, the last handling being postponed to a later stage in the cycle of lasting room operations in order to facilitate the operation of the present machine and to provide for the insertion of lasts under circumstances more conducive to ease of last handling. Preferably, the last insertion will be performed immediately after the operation of the present machine in conjunction with the operation of a machine for attaching insoles to last bottoms. Heretofore the insole has been attached to the last bottom in advance of the operation of the counter inserting machine. The system contemplated by the present invention permits the period of last rotation to be shortened very substantially thus permitting economies in last supply and maintenance.

It is a further object of the invention to provide, instead of the last supporting and positioning instrumentalities common to machines of this type, a heel form which is automatically actuated in connection with the upper shaping operations. The provision of a heel form results in more reliable and uniform work and a higher rate of machine production.

With the above and other objects in view, as will hereinafter appear, the present invention, in one aspect thereof, consists in the provision in a shoe machine, of a carrier for inserting a counter into a shoe upper supported in the machine, a carrier for moving an insole heelwardly into the supported upper while the upper is tensioned lengthwise by gripping means engaging the bottom margin at opposite sides of the heel end portion of the upper, and means for fastening together the upper, the counter

2

and the insole while the heel end portion of the upper is under tension.

While the insole carrier is illustrated in the drawings in combination with counter inserting and heel end tensioning means it is to be understood that the invention, in its relation to the insole carrier, is not limited to the combination thereof with either the counter inserting means or the upper tensioning means but is applicable generally to shoe supporting means in combination with the insole carrier and means for operating the carrier to insert an insole thereon into the shoe upper assembly.

The illustrated insole carrier serves not only to insert an insole into the shoe upper assembly but also to apply shaping pressure to the inner surface of the back line portion of the upper. To that end the illustrated machine is provided with means for advancing the carrier heelwardly while the breast line grippers are urged toward to apply lengthwise tension to the upper. It is to be understood that in its application to means for applying lengthwise tension to the heel end portion of a shoe upper, the present invention contemplates the employment of a heel form which may or may not perform the additional function of inserting an insole into shoe upper parts supported in the machine.

In its application to counter handling means the present invention contemplates the provision of a conveyor constructed and arranged to mount a plurality of counters and to advance the counters respectively to a leading station in which the counter is arranged in predetermined relation to the carrier, the conveyor assembly being arranged to advance bodily from the leading station to a loading station in which the counter is transferred from the conveyor to a counter carrier. The illustrated conveyor is operated in measured steps to advance the counters thereon one by one into the leading station. In the illustrated organization the conveyor comprises a member mounted in a carriage for step-by-step movement relatively thereto to advance a counter into the leading station, the carriage in turn being advanced to transfer a counter from the leading station to a loading station relatively to a carrier which receives a counter from the conveyor member and transfers it to a shoe upper supported in the machine. The conveyor, as illustrated in the drawings, comprises a chain mechanism having incorporated therein elements for mounting a plurality of counters.

The conveyor transmits a counter to the counter carrier which operates first to immerse a counter thereon in fluid, for example adhesive cement, in an immersion vessel and thereafter operates to insert the treated counter into a supported upper. The illustrated counter carrier is operable manually to transfer a counter from the loading station to the immersion or coating station and is operable by power to transmit a coated counter to the supported upper.

The illustrated machine is provided with suitable means for determining the orientation of a counter in the coating station and with means for determining the orientation of the counter in the supported upper. The orientation of the counter is effected automatically by means operating during movement of the carrier between the coating station and the inserting station.

In order to facilitate the upwiping of the quarter lining against the inner or concave surface of a counter mounted in the supported upper, the illustrated counter carrier is provided with a counter spreader constructed and arranged to move the wings of the counter away from each other. For operating the spreader there is provided a member, illustrated in the drawings as a cam, which is freely movable between an operative and an inoperative position, means illustrated as a detent for holding the cam member in its operative position and means

for retracting the detent to permit the return of the counter spreading means to its inoperative position. In the illustrated organization the detent is retracted by the lining wiper at a predetermined stage in the lining wiping operation.

The illustrated counter handling mechanism is characterized by the construction and arrangement of the counter conveyor to grip the top margin of the counter in the region of the back line and to orient the counter for presentation to the counter carrier by means which serves to position the counter wings heightwise thereof. The illustrated conveyor comprises a carriage in which is mounted a carrier chain provided with means for gripping the top margin of the counter in the region of the back line, the carriage having incorporated therein the means for positioning the counter wings heightwise thereof. The illustrated wing positioning means comprises a pair of guide rails which are retractable to admit a plurality of counters into the conveyor assembly.

It is to be understood that the invention in its application to counter conveying means is not limited to the illustrated combination of the conveyor assembly with means for inserting a counter into a supported upper since such an organization would be applicable to other types of machines such, for example, as counter molding machines.

The illustrated conveyor assembly is characterized by a pawl and ratchet mechanism for advancing the counter carrying chain step by step relatively to the carriage thereby to advance a counter into the leading station relatively to the carriage and is further characterized by means for advancing the carriage thereby to transfer a counter from the leading station to a loading station where it is transferred to the carrier which inserts the counter into the supported upper. The illustrated pawl and ratchet mechanism indexes the chain relatively to the carriage by increments corresponding to the distance between adjacent counters on the chain.

Counters are shipped to the illustrated machine in a suitable package or box in which the counters are so mounted that a box full of counters can be loaded in the conveyor in a single operation, and to that end the carriage is provided with means for locating a box in predetermined relation to the counter supporting elements of the conveyor.

The illustrated organization for applying longitudinal tension to the heel end portion of a shoe upper in the machine includes grippers which engage and support an inverted shoe upper in the region of the heel breast line and power operated means for moving the heel form heelwardly into the supported upper. In conjunction with its heelward movement the heel form is moved heightwise of the upper into engagement with abutment means which causes a predetermined orientation of the heel form relatively to the supported upper. The illustrated heel form is characterized by retractable means for positioning an insole relatively to the heel form, said positioning means being illustrated in the drawings as pins extending convergently from the heel form through suitable apertures in the insole. The illustrated heel form is provided with manually operable cam means for advancing the pins into insole engaging position and for retracting them from the insole and into the heel form.

For fastening a supported upper to an insole the present invention contemplates the provision of a wiper operating locally on a portion of the lasting margin of the upper to wipe it inwardly over the margin of an insole and an actuator which operates first to advance the wiper and thereafter to cause a driver to insert a fastening through the overwiped margin of the upper and the margin of the insole.

These and other features of the invention will now be described with reference to the accompanying drawings and pointed out in the appended claims.

Wherever the following description identifies only one of two assemblies performing like operations at opposite sides of a shoe upper in the machine it will be understood that the description applies not only to the assembly identified but also to the companion assembly.

In the drawings,

Fig. 1 is a right side elevation of a machine embodying the features of the present invention;

Fig. 2 is a right side elevation illustrating the back line gripper mechanism, one of the back line wiper members, and the lining wipers, the back line gripper mechanism being shown in gripping engagement with the heel end portion of a shoe and the back line wiper members and the lining wipers being shown in retracted position;

Fig. 3 is a plan view illustrating the back line gripper mechanism and one of the back line wipers in their respective positions shown in Fig. 2;

Fig. 4 is an enlarged view in right side elevation illustrating the gripper mechanism operating at the junction of the back line and the top line;

Fig. 5 is a detail view in front elevation illustrating the back line gripper assembly shown in Fig. 4;

Fig. 6 is a plan view of the back line gripper assembly illustrated in Fig. 4;

Fig. 7 is a right side elevation of the gripper jaws shown in Fig. 4 with the forward jaw shown in section on the line 7—7 of Fig. 5;

Fig. 8 is an enlarged plan view similar to Fig. 6 partly in section on the line 8—8 of Fig. 7;

Fig. 9 is a section taken on the line 9—9 of Fig. 4;

Fig. 10 is a right side elevation illustrating particularly the mechanism for operating the back line grippers;

Fig. 11 is a sectional view of the heel end portion of a shoe upper looking heelwardly into the upper and illustrating particularly a quarter lining which has been notched to facilitate the registration of the upper with the jaws of the lower back line gripper;

Fig. 12 is a sectional view of the heel end portion of a shoe upper mounted in the back line gripper jaws and having the quarter lining drawn forwardly and downwardly to provide clearance for the insertion of a counter into the upper;

Fig. 13 is a right side elevation illustrating the counter carrier assembly with a mounted counter molded therein, various positions of the counter carrier being indicated in broken lines;

Fig. 14 is a plan view of the mechanism shown in Fig. 13 with a portion of a counter mounted in the counter carrier;

Fig. 15 is a front elevation of the counter carrier assembly;

Fig. 16 is an enlarged plan view of the counter carrier assembly and a portion of a counter molded therein;

Fig. 17 is an enlarged view in side elevation illustrating the counter carrier;

Fig. 18 is a section on the line 18—18 of Fig. 17;

Fig. 19 is a plan view of the mechanism for operating the counter carrier, partly in section, on the line 19—19 of Fig. 10;

Fig. 20 is an enlarged detail view of a portion of the mechanism shown in Fig. 16;

Fig. 21 is a section taken on the line 21—21 of Fig. 20;

Fig. 22 is a front elevation of the counter conveyor with a plurality of counters mounted therein, the central portion of the conveyor being broken away;

Fig. 23 is a right side elevation of the counter conveyor illustrated in Fig. 22, the central portion of the conveyor being broken away;

Fig. 24 is a plan view of the counter conveyor with certain parts broken away to permit the illustration of underlying mechanism, a counter container with its upper end broken away being shown in position to permit transfer of the counters therein to the conveyor;

Fig. 25 is a plan view similar to Fig. 24 showing the

arrangement of certain operating parts of the counter conveyor after the counter container is removed therefrom;

Fig. 26 is a perspective view illustrating a portion of the counter conveyor;

Fig. 27 is a detail view illustrating a portion of the left side of the counter conveyor assembly;

Fig. 28 is a section taken on the line 28—28 of Fig. 24;

Fig. 29 is a section taken on the line 29—29 of Fig. 28;

Fig. 30 is an enlarged view illustrating the lower end portion of the counter conveyor, and the lowermost counter thereon in relation to a counter gripping means on the counter carrier;

Fig. 31 is an enlarged view similar to Fig. 30 showing the position of the lowermost counter on the conveyor relatively to the gripping means in the counter carrier at the point in the operation of the counter conveyor assembly when the slide mounting the counter conveyor is at the limit of its downward movement;

Fig. 32 is an enlarged view similar to Fig. 31 illustrating the relative position of the counter and the gripping means on the counter carrier after the counter has been mounted on the carrier;

Fig. 33 is a detail view looking in the direction of the arrow in Fig. 32 showing the gripping means on the counter carrier and a counter thereon in the same relation to the gripping means as shown in Fig. 31;

Fig. 34 is a right side elevation illustrating the counter carrier assembly and a counter thereon in draining position relatively to the immersion tank, the heel end portion of an upper being shown in the black line gripper jaws;

Fig. 35 is a front elevation illustrating parts of the mechanisms for operating the counter conveyor and the counter carrier;

Fig. 36 is an enlarged detail view of a portion of the mechanism shown in Fig. 35;

Fig. 37 is a plan view, partly in section, on the line 37—37 of Fig. 35, illustrating the mechanism shown in Fig. 36;

Fig. 38 is a section taken on the line 38—38 of Fig. 37;

Fig. 39 is a plan view of a container constructed to mount a predetermined number of molded counters in fixed relation to each other, the central portion of the container being broken away and a plurality of counters being shown in the container;

Fig. 40 is a bottom view of the container together with a plurality of counters therein, the central portion of the container being broken away as in Fig. 39;

Fig. 41 is a side elevation of the container and the counters therein with the central portion of the container broken away and with the upper portion of the container shown in section in order to illustrate the means for mounting the counters therein;

Fig. 42 is a section taken on the line 42—42 of Fig. 39;

Fig. 43 is a right side elevation showing the counter carrying mechanism at the end of its counter inserting movement and showing the lining wiper mechanism in its retracted position;

Fig. 44 is a plan view illustrating a portion of the lining wiper operating mechanism illustrated in Fig. 43;

Fig. 45 is a section taken on the line 45—45 of Fig. 44;

Fig. 46 is a section taken on the line 46—46 of Fig. 43;

Fig. 47 is a section taken on the line 47—47 of Fig. 44;

Fig. 48 is an enlarged view in right side elevation illustrating the lining wipers and the upper end portion of the wiper carrier;

Fig. 49 is a plan view of the mechanism illustrated in Fig. 48;

Fig. 50 is a right side elevation similar to Fig. 48 with the lining wipers removed from the carrier;

Figs. 122 and 123 are cam charts.

As illustrated in the drawings, the present invention is embodied in an automatic machine which combines means for supporting a shoe upper by engagement therewith at opposite ends of the back line, means for inserting into the supported upper a counter coated with fluid adhesive, means for automatically inserting a heel form into the supported upper, means for shaping the heel end portion of the upper over the heel form, and means for fastening the bottom margin of the upper together with the margins of the lining and the counter to an insole positioned in predetermined relation to the bottom of the heel form.

For positioning and supporting the heel end portion of a shoe upper relatively to the operating instrumentalities the machine illustrated in the drawings is provided with a back line gripper comprising a pair of jaws constructed and arranged to engage the upper and the lining at the junction of the back line and the top line and a second back line gripper comprising a pair of jaws constructed and arranged to engage the upper only at the junction of the back line and the lasting margin. The position of the heel form lengthwise of the shoe during the upper fastening operation is determined by an abutment member constructed and arranged for engagement by the back line portion of the upper at the end of the rearward movement of the heel form. In order to provide for the positioning in the machine of shoe uppers having different back line contours each of the back line grippers is adjustable longitudinally of the shoe upper. In order to provide for the positioning in the machine of shoe uppers of different sizes the gripper at the junction of the back line and the top line is adjustable heightwise of the upper relatively to the gripper at the junction of the back line and the lasting margin which remains in a fixed position heightwise of the shoe in order to determine accurately the position of the bottom margin of the upper

relatively to the plane in which a plurality of upper shaping wipers operate.

The illustrated machine is provided with a conveyor constructed and arranged to receive a plurality of molded counters from a container. The conveyor is operated automatically to mount a molded counter on a counter carrier. The counter carrier operates to immerse the counter into a bath of fluid adhesive and then operates in a reverse direction to lift the counter into a position in which excess adhesive on the counter drains into the tank. During the first part of the machine cycle the counter carrier transfers a coated counter from its draining position to a position in which the counter is accurately located in the heel portion of the supported upper. The counter carrier holds the counter in the upper until a plurality of heel pads engage the heel end portion of the upper to maintain the relative position of the counter and the upper on the heel form. After the pads have taken control of the counter the carrier is retracted to provide clearance for the operation of the wipers. The retraction of the carrier is arrested when the carrier, now unloaded, reaches its loading station. While the carrier remains in its loading station the conveyor is moved bodily downwardly into its operating position and is actuated by a suitable indexing mechanism to transfer the lowermost counter on the conveyor to the counter carrier. Thereupon the counter carrier moves downwardly to immerse the counter therein in the bath of fluid adhesive and then moves upwardly into counter draining position. The counter remains in draining position during the last third of the main cycle of the machine and thereafter until the beginning of the counter inserting movement of the carrier in the next cycle of the machine.

While a treated counter is supported by the counter carrier in the heel end portion of the upper a pair of lining wipers are operated to bring the quarter lining of the supported upper into intimate contact with the inner or concave surface at the back line portion of the counter. In the illustrated machine the lining wipers are manually operated, the main power cycle of the machine having been interrupted after one third of its operation to permit the operation of the lining wipers and other instrumentalities. The upward movement of the lining wipers also serves to position the bottom margin of the lining at opposite sides thereof between the jaws of grippers positioned in the region of the breast line portion of the upper and concomitantly the bottom margin of the upper at opposite sides thereof is manually positioned between the jaws of grippers positioned adjacent to the lining grippers above referred to. As the lining wipers begin their downward or retracting movement the gripper jaws are automatically released for closing movement. While the interruption of the main cycle of the machine continues the operation of a separate power mechanism is initiated to cause the heel form to be advanced automatically into the heel end portion of the supported upper. The heel form engages the back line portion of the quarter lining and moves the upper heelwardly until the space between the outer portion of the upper and an abutment member is taken up and the upper is firmly seated against the abutment member. The rearward movement of the heel form imparts tension to the upper on lines extending from the mid section of the back line to the points of engagement of the breast line grippers at opposite sides of the heel portion of the upper.

The heel form carries on its sole face an insole which is positioned by the heelward movement of the form for the subsequent wiping and fastening operations. To provide for the accurate registration of the heel end portion of the insole with the heel end portion of the upper two holes are punched in predetermined positions in the heel portion of the insole to receive pins projecting from the heel form. These pins not only determine the position of the insole relatively to the form but also hold the insole

on the form during the heelward movement of the form into the upper and thereafter during subsequent operations of the machine. After the heel form has been brought into position in the supported upper the lining wiper assembly is again moved upwardly to bring a supporting plate mounted on the wiper carrier and positioned above the lining wipers into engagement with the bottom of the heel form. Such upward movement of the lining wiper assembly lifts the heel form slightly to bring the insole into intimate contact with the margin of the lining, at least at the back line portion of the upper where the counter flange lies substantially parallel to the insole. Upon the completion of the upward movement of the lining wiper assembly into supporting engagement with the heel form a wedge is advanced into position to support the lining wiper assembly against downward movement during the subsequent wiping and fastening inserting operations.

After the advancement of the wedge the second third of the main cycle of the machine is initiated to bring into operation the breast line grippers and the upper engaging pads. At an early stage in the second third of the cycle a pair of cams impart toeward movement to the breast line gripper jaws establishing lines of tension from the breast line gripper jaws to the gripper at the junction of the back line and the lasting margin and also to the gripper at the junction of the back line and the top line. Concomitantly with the advancement of the breast line gripper jaws the upper engaging pads are advanced into upper engaging position and after the completion of the advancement of the breast line gripper jaws and while they are maintained at the limit of their toeward movement additional pressure is applied to the upper engaging pads in order to maintain the tension imparted to the upper after the breast line grippers are opened and retracted and until the breast line wipers have wiped the upper in over the insole and tacks have been driven and clenched to secure the upper, together with the counter and the lining, to the margin of the insole.

Upon the completion of the second third of the main cycle the machine again comes to rest to permit inspection of the work. During the last third of the cycle the breast line wipers and the back line wipers are advanced concomitantly to wipe the bottom margin of the upper in over the insole at selected points. In the illustrated organization four wipers are provided two of which operate at opposite sides of and adjacent to the back line while the other two operate at opposite sides of the heel portion of the upper in the region of the breast line. Upon the completion of the wiping operation tacks are driven through suitable apertures in the wiper members to secure the upper, together with the counter and the quarter lining, in overwiped relation to the insole, the tacks being clenched against the upper surface of the metal heel form.

The invention also contemplates the attachment of the bottom margin of the upper together with the flange of the counter and the margin of the quarter lining to the insole by a suitable adhesive if it is desired to avoid the use of metallic fastenings in securing the shoe upper parts to the insole. To this end a removable cap or ferrule is provided for each of the four wiper members. The cap serves as the wiping element and the tack driving pin in each of the wiper assemblies is operated to deliver a hammer blow to the cap in order to insure an effective bond of the bottom marginal portions of the shoe parts to each other and to the insole.

Upon the completion of the wiping and fastening operations a cam operates the clutch which controls the operation of the automatic mechanism for actuating the heel form and thereupon the main cycle of the machine is terminated. The heel form is then moved forwardly out of the wiping and tacking station of the machine and returned to its rest position. It will be understood that during its return movement the heel form carries with it the insole and the shoe upper parts which have been assem-

bled therewith and secured thereto. After the heel form comes to rest in its retracted position the operator retracts the insole retaining pins by means of manually operated mechanism incorporated in the heel form whereupon the assembled shoe parts are removed from the heel form and another insole is positioned thereon. After positioning the insole in proper relation to the heel form, the retaining pins are advanced by the operation of the mechanism above referred to, to retain the insole on the heel form during the next succeeding cycle of the machine.

Referring to Fig. 1 the illustrated machine comprises a table 130 mounted on four legs, the two legs at the left side of the table being identified by the numeral 132 and the two at the right side by the numeral 134. Projecting upwardly perpendicularly from the center of the forward portion of the table are two parallel standards or plates 136 on which there are mounted a counter carrier assembly, the breast line gripper assemblies and other operating instrumentalities of the machine. Projecting upwardly from the rear portion of the table 130 is a superstructure 138 having incorporated therein means for mounting an inverted bottle 140 containing fluid adhesive. The bottle is positioned above a counter immersion tank 142 and maintains a constant level of fluid in the tank. Positioned rearwardly of and adjacent to the standards 136 is a standard 144 which provides a guideway for a slide 146 which mounts the counter conveyor mechanism.

The motive power for the automatic mechanism of the machine is provided by a motor 148 suitably mounted between the rear legs of the machine. A pulley 150 fixed to the motor shaft transmits power through a suitable belt 152 to a large pulley 154 mounted to turn freely on a drive shaft 156. A small pulley 158 which rotates with the large pulley 154 transmits power through a suitable belt 160 to a pulley 162 fixed to a drive shaft 164. Upon the operation of a suitable clutch mechanism the shaft 164 operates through mechanism hereinafter described to actuate a metal heel form 166.

Referring to Fig. 121 the pulley 154, when connected to the drive shaft 156 by a suitable one-revolution clutch mechanism, rotates a spur gear 168 fixed to the shaft 156 and arranged to mesh with a large spur gear 170 fixed to a cam shaft 172. The small gear 168 operates at a 3 to 1 ratio to the large gear 170 so that three complete revolutions of the drive shaft 156 are required to complete the operating cycle of the cams on the shaft 172. Cooperating with the cams on the shaft 172 in the performance of the various operations comprising the main cycle of the machine are a plurality of cams mounted on two vertical cam shafts 174 and 176 and a horizontal shaft 178 positioned above the shaft 172 and arranged at right angles to a vertical plane common to the shaft 172. The two vertical cam shafts 174 and 176 are actuated by a bevel gear 180 fixed to the rear end portion of the cam shaft 172 and arranged to mesh with a bevel gear 182 fixed to the upper end portion of the vertical cam shaft 176 and a bevel gear 184 fixed to the lower end portion of the vertical cam shaft 174. The horizontal cam shaft 178 is actuated by a bevel gear 186 fixed to the upper end portion of the vertical cam shaft 174 and arranged to mesh with a bevel gear 188 fixed to the horizontal cam shaft 178. The bevel gear 188 also operates a bevel gear 190 fixed to the lower end portion of a short vertical cam shaft 192. The bevel gears all operate at a 1 to 1 ratio so that three revolutions of the drive shaft 156 are required to complete the cycle of operations of all of the cams which operate in the main cycle of the machine.

Fixed to the drive shaft 164 is a small spur gear 194 which meshes with a large spur gear 196 mounted to rotate freely on a cam shaft 198. The gear 196 operates the cam shaft 198 through a suitable clutch mechanism to actuate the mechanism for operating the heel form 166.

At the end of one complete revolution of the drive shaft 156 the rotation of the shaft is automatically ar-

5 rested thus interrupting the main cycle of operations of the machine. It will be understood that at this point one third of the main cycle of operations has been performed and the second third of the operations will be 10 performed when the clutch on the drive shaft 156 is again operated to connect the shaft to the driven pulley 154. While the main cycle is interrupted at the end of the first third of the operations in the main cycle a treadle 200 (Fig. 1) is operated to actuate the lining wipers and to 15 perform other operations hereinafter described and a hand lever 202 (Fig. 79) is operated to cause the clutch on the cam shaft 198 to be actuated in order to connect the shaft to the constantly rotating gear 196. The cam shaft 198 rotates 180° and is then brought to rest by the operation of a cam 204 which disengages the clutch from the gear 196. Mechanism hereinafter described actuated by the cam shaft 198 advances the heel form 166 in an arcuate path into the forepart of a shoe upper supported in the machine and then advances the heel form heelwardly into engagement with the back line portion of the quarter lining, the advancement of the heel form being arrested by an abutment member 206 (Fig. 2). The rotation of the cam shaft 198 terminates upon the completion of the heelward movement of the form 166 25 and the cam shaft remains at rest with the heel form in this position until the latter part of the main cycle of the machine when a cam 1344 (Fig. 121) on the shaft 172 automatically operates the clutch on the cam shaft 198 to cause the cam shaft to rotate 180° thereby to retract the heel form 166 with the upper and return it to its rest position illustrated in Fig. 1.

30 The main cycle of the machine is interrupted a second time after the completion of the second third of the operations therein in order to permit the operator to inspect the work before starting the last third of the main cycle. The second interruption occurs after the counter holder has been retracted from its position shown in Fig. 43 in which it supports the counter in the heel portion of the upper. At this time the feather line pads have been 35 advanced to grip the feather line portion of the upper against the heel form preparatory to the wiping and tacking operations and the mechanism for advancing the feather line pads has applied gripping pressure to the top line pads to complete the gripping engagement of the heel end portion of the upper against the heel form. Any minor correction of the position of the upper or the counter which may be required can be made at this time with any suitable tool such, for example, as hand pincers, 40 before the main clutch is again operated to start the last third of the main cycle.

45 Referring to Figs. 2 and 4, the gripper which engages the upper at the junction of the back line and the top line comprises a forward jaw 208 having teeth in its convex rear surface constructed and arranged to engage a portion of the quarter lining adjacent to the top line of the upper. Cooperating with the forward gripper jaw is a rear jaw 210 formed in the forward portion of a lever 212 which is swung in a counterclockwise direction, as seen in Fig. 4, to close the jaws on the work. To provide 50 for the pivotal mounting of the lever 212 its forward portion is extended downwardly and has a cross pin 218 fixed therein. Referring to Fig. 7, the cross pin is mounted for turning movement in bearings in a block 219 and for sliding and turning movements in bearings 55 in the bifurcated forward portion of a plate 220 secured by a clamping screw 246 (Fig. 7) to the horizontal portion of an angle bracket 244 mounted on a standard 248 (Fig. 4). The block is held against angular movement by the engagement of its plane bottom surface with the upper surface of the horizontal arm of the bracket 244. As shown in Fig. 7, the block 219 is recessed to receive 60 the forward portion of the lever 212. To provide for downward movement of the forward jaw 208 from its position in Fig. 7 to its position in Fig. 64 in order to 65 provide clearance for movement of the upper out of

the machine with the heel form the forward jaw 208 is formed at the upper end of a bar 221 which is slidably mounted in a dove-tail groove 223 (Fig. 8) formed in the inclined forward surface of the block 219. The bar 221 has formed therein a tongue 225 constructed and arranged to slide in the groove 223 and the bar is urged downwardly by a spring 227 mounted in a longitudinal groove 267 formed in the tongue and confined between the lower end wall of the groove and a pin 229 mounted in the block 219 and extending into the groove 267. The spring is retained in the groove by a downward extension 231 of the block 219. During the operation of the grippers the bar 221 is held in its uppermost position shown in Fig. 7 by a latch 233 formed at the forward end of a slide 235 mounted for horizontal movement in a guideway formed in an arm 237 projecting rearwardly from the lower extremity of the extension 231. The slide 235 is urged forwardly by a spring 239 (Fig. 4) the forward end of which is anchored to a web projecting rearwardly from the extension 231 and the rear end to a pin 241 projecting upwardly from the slide 235 through a slot in the arm 237. At the appropriate time in the machine cycle the slide 235 is retracted to permit the spring 227 to move the bar 221 downwardly into its position shown in Fig. 64, the downward movement of the bar terminating upon the engagement of the upper end wall of the groove 267 with the pin 229. The retraction of the slide 235 is effected during the downward movement of a rod 294 which moves the lever 212 downwardly to open the gripper jaws 208 and 210. As shown in Fig. 4, the rod 294 has fixed thereto a collar 243 having hinged thereon a cam 245. The cam is a U-shaped member constructed and arranged to straddle the reduced lower portion of the collar and is normally held in its position illustrated in Fig. 4 by a leaf spring 224 mounted in a recess in the collar and arranged to engage a forwardly extending tail portion of the cam thereby to urge the cam in a counterclockwise direction against the body portion of the collar. The orientation of the cam 245 is maintained by a pin 222 mounted in a rearward extension of the angle bracket 244 and projecting into a longitudinal groove in the rod 294 to hold the bar against turning movement. During the downward movement of the rod the cam 245 engages an angular surface 247 projecting forwardly and downwardly from the rear wall of a hollow square extension 249 of a slide 251. During the upward movement of the rod 294 the cam 245 is swung idly in a clockwise direction by its engagement with the extension 249 and is restored to its horizontal position by the spring 224 after it clears the extension. The slide 251 is mounted for horizontal movement in a guideway in a block 253 fixed to the standard 248 and is connected by a slide 255 to the rear end portion of the slide 235. The slide 255 moves vertically with the bracket 144 during the adjustment of the gripper jaws heightwise of the upper and in order to accommodate such adjustment the slide 255 has a vertically elongate head 257 which is slotted to receive a pin in the bifurcated forward end portion of the slide 251. In order to accommodate adjustment of the gripper jaws lengthwise of the upper the slide 255 comprises a stem slidably mounted in a sleeve and secured in adjusted position therein by a setscrew 259. In order to accommodate adjustment of the gripper jaws widthwise of the upper the sleeve has a horizontally elongate channel head 261 at its forward extremity in which is slidably mounted a head 263 formed at the rearward extremity of the downwardly offset portion of the slide 235. To facilitate the upward movement of the forward jaw to return it to its operating position shown in Fig. 7 a finger grip 265 is formed at the lower extremity of the bar 221. As the gripper jaw comes to the limit of its upward movement the spring 239 advances the latch member 233 into position to hold the jaw against downward movement. For determining the position of the back line portion of

a shoe upper heightwise thereof in the machine the rear gripper jaw 210 has a forward extension 214 (Fig. 4) positioned below and adjacent to the gripping teeth and arranged to support the back line portion of the upper 5 in the open gripper jaws by engagement with the top edge of the upper in the region of the back line. The forward portion of the extension 214 has the form of an arc struck from the fulcrum of the lever 212 thus obviating upward displacement of the upper by the extension 214 during the clockwise movement of the lever 212 to open the gripper jaws. In order to permit a limited adjustment of the gripper assembly endwise of the cross pin 218 the block 219 (Fig. 8) is spaced from the bifurcated forward portion of the plate 220. The gripper assembly is normally maintained in a central position 10 relatively to the plate 220 by two springs 228 (Fig. 6) mounted on the cross pin 218 and confined between the opposite side faces of the plate 220 and two collars 230 secured to the opposite end portions of the cross pin. 15 To provide for the retention of the gripper assembly in any adjustable position endwise of the cross pin two spring pressed latch plates 232 are pivotally mounted between ears 234 (Fig. 4) projecting forwardly from the collars 230 respectively and the latch plates have stepped inner 20 end portions (Fig. 6) constructed and arranged to engage the forward extremities of the plate 220. The adjustment of the gripper assembly endwise of the cross pin permits the positioning of the back line portion of the upper in the proper angular relation to the plane of the heel end 25 portion of the insole. Referring to Figs. 11 and 12, the back line portion of the upper is positioned relatively to the jaw 208 by causing a notch 236 formed in a quarter lining 238 at the junction of the back line and the top line to register with a tooth 240 formed in the jaw 208 and visible through an arched opening 242 formed therein. 30 To provide for the vertical adjustment of the gripper assembly in accordance with the size of a shoe upper to be operated upon the angle bracket 244 (Fig. 2) is adjustable vertically relatively to the fixed standard 248 and is secured in adjusted relation to the standard by clamping means comprising a headed bolt 250 and a hand nut 256. The bolt is slidably mounted endwise in a bore in the angle bracket and the standard 248 is slotted vertically to provide for the adjustment of the 35 angle bracket. The adjusted position of the angle bracket is indicated by the registration of an arrow on the right edge face of the angle bracket with a suitable scale inscribed on a plate 252 secured to the standard. The angle bracket is positively held in adjusted position by 40 the engagement of the serrated forward face of the head 254 of the bolt 250 with teeth formed in the rear margin of the scale plate 252. The gripper operating at the junction of the back line and the lasting margin comprises a fixed rear jaw 258 45 (Fig. 2) formed in the forward extremity of an angular extension of a plate 260 secured by a clamping screw 262 to an arm 264 extending forwardly from the upper end portion of the standard 248. Cooperating with the fixed jaw 258 is a movable jaw 266 constructed and 50 arranged to engage the inner surface of the upper. As herein illustrated the movable jaw 266 is formed at the extremity of an arcuate forward extension of a lever 268 pivotally mounted at a point adjacent to its arcuate extension between ears 270 formed in the plate 260 at 55 the junction of the body portion of the plate and its angular extension. To provide for the adjustment of the back line gripper assemblies bodily longitudinally of a shoe upper in the machine relatively to each other in order to accommodate shoe uppers having different back line contours, the plate 260 is adjustable lengthwise of the upper on the arm 264 and the plate 220 is similarly 60 adjustable on the angle bracket 244. In each case the adjustment is indicated by the registration of index marks on the arm 264 and the angle bracket 244, respectively, 65 with suitable scales inscribed on the plates. The abut- 70

ment member 206 is also mounted for adjustment toward and from the back line portion of a shoe upper in the machine to accommodate different back line contours. As shown in Fig. 2, the abutment member comprises a resilient pad 272, made of leather or the like, secured to a concave shoe 274 having a ball and socket mounting in a member 276 supported on a stem 278 at the forward end of a screw 280 and held against movement endwise of the screw by the engagement of a pin 282 in the member 276 in a circumferential groove 284 formed in the stem 278. The screw 280 is mounted in a threaded bore in the standard 248 and is adjustable therein to determine the position of the abutment member relatively to the upper, the screw 280 being secured in adjusted position by a set screw 286. The member 276 is held against angular movement about the stem 278 by a pin 288 mounted in the member 276 and extending rearwardly therefrom for sliding engagement in a suitable bore in the standard 248.

For closing both pairs of back line gripper jaws simultaneously the illustrated machine is provided with a spring 290 which acts on the lever 212 and a spring 292 which acts on the lever 268. Each of these springs surrounds the rod 294 slidably mounted in alined bores in arms 296 and 298 extending rearwardly from the standard 248. The spring 290 acts through collars 300 mounted on the rod 294 and the uppermost of said collars acts on the rounded end portion 302 of the lever 212. The spring 292 acts on a collar 304 at the upper end of the rod 294, the rounded end portion 306 of the lever 268 being mounted on the collar. In order that both pairs of gripper jaws will be fully closed regardless of the relative thickness of the upper materials at opposite ends of the back line the collar 304 is mounted to slide on the rod 294 and the collars 300 are so adjusted that the upper jaws 258 and 266 will close first and the rod 294 will move upwardly relatively to the collar 304 during the final stage of the closing movement of the lower jaws 208 and 210. When the machine is at rest both pairs of back line gripper jaws are held open by a latch 308 (Fig. 10) which acts on a tooth projecting forwardly from the lower end portion of a slide 310 mounted for vertical movement in suitable guideways formed in standards 312 (Fig. 60) secured to the lower structure of the frame beneath the table 130. Pivottally mounted at the upper end portion of the slide 310 is a collar 314 fixed to the lower end portion of the rod 294. To permit the back line gripper jaws to close on the work the latch 308 is retracted by the depression of a treadle 316 (Fig. 1) pivotally mounted at 318 on a bracket at the rear of the machine. As shown in Fig. 10, the treadle 316 is connected by a link 320 to the free end of an arm 322 mounted to swing with the latch 308.

Just prior to the operation of the wiper members the back line gripper jaws are automatically opened to leave the bottom margin of the upper free to be wiped inwardly over the insole and to leave the upper free of the lower back line gripper jaws 208 and 210 so that it may be removed from the machine upon completion of the machine cycle. Referring to Fig. 10, a cam 324 fixed to the vertical cam shaft 176 engages a roll 326 on a lever 328 at the appropriate time in the main cycle and swings the lever in a counterclockwise direction, as seen in Fig. 10, about its fulcrum 330, thus imparting downward movement to a link 332 connecting the forward end of the cam lever to a lug 334 projecting rearwardly from the slide 310. Upon the completion of the downward movement of the slide by the cam lever 328 a spring 336 on the arm 322 swings the latch 308 into its latching position shown in Fig. 10 in order to hold the back line gripper jaws open until the treadle 316 is again operated. Referring to Fig. 4, after the rod 294 has moved downwardly far enough to take the pressure of the jaw 210 off the shoe upper the cam member 245 engages the surface 247 and operates through the slides 251, 255 and

235 to retract the latch member 233 thus permitting the spring 227 (Fig. 7) to move the jaw 208 downwardly into its position shown in Fig. 64 in order to provide clearance for the movement of the upper toewards out of the operating station.

The illustrated machine is provided with means for opening the back line grippers prior to the initiation of the main power cycle of the machine in the event that a correction of the position of the shoe upper in the grippers is required. In the illustrated organization the opening of the gripper jaws is effected by downward movement of a hand lever 338 (Fig. 2) fixed to a shaft 340. Referring to Fig. 34, a short arm 342 fixed to the central portion of the shaft is bifurcated to engage a pin projecting laterally from a collar 344 fixed to the rod 294. Downward movement of the hand lever 338 moves the rod 294 downwardly to open the back line gripper jaws and the latch 308 (Fig. 10) holds the gripper jaws open until the treadle 316 is again operated to disengage the 20 latch and permit the gripper jaws to close.

At the beginning of the main cycle of the machine the back line gripper jaws are further closed by the operation of a cam 346 (Fig. 10) fixed to the shaft 172 and arranged to actuate a bell crank lever 348 pivotally mounted at 350 at the lower end of the rear arm of a bracket 352 fixed to the machine frame. At the rear end of its horizontal arm the bell crank lever 348 carries a detent 354, said detent being slidably mounted in an angular head 356 formed integrally with the bell crank lever. The detent is yieldingly held in its advanced position shown in Fig. 10 by a spring 358 mounted in a suitable bore in the head and the detent is oriented by a pin 360 mounted therein and extending laterally through a slot in the head 356. The detent acts against 30 ratchet teeth at the lower end of an arm 362 fixed to the shaft 330 and urges the arm in a clockwise direction. The shaft 330 has fixed thereto the cam lever 328 and the operation of the arm 362 urges the forward end of the cam lever upwardly which, as hereinbefore described, 35 is connected by the link 332 and the slide 310 to the rod 294 which operates by upward movement thereof to impart closing action to both of the back line grippers.

Referring to Fig. 13, the illustrated machine is provided with means for transferring a molded counter from a loading station to a lined upper supported by the back line grippers. In the illustrated organization the transferring means is a counter inserter or carrier constructed and arranged to receive a molded counter such, for example, as the counter 364, from a counter conveyor hereinafter described. The counter carrier, upon receipt 45 of the counter from the conveyor, advances in a clockwise direction, as seen in Fig. 13, to immerse the counter in fluid adhesive in the tank 142 (Fig. 34) and then swings in a counterclockwise direction just enough to raise the counter into a position in which excess adhesive fluid drains from the counter into the tank. During the next main cycle of the machine the counter carrier swings in a counterclockwise direction to advance the counter from its draining position into its position in the heel 50 end of the supported upper, as illustrated in Fig. 43. The illustrated counter carrier is fixed to a shaft 366 (Fig. 14) mounted to rotate in suitable bores in alined bosses 368 projecting inwardly from the standards 136 (Fig. 15). For actuating the counter carrier a cam 370 (Figs. 10 and 19) is fixed to the vertical cam shaft 176. The cam 370 has formed in its upper surface an irregular path or groove 372 in which is mounted a roll 374 mounted on a pin extending downwardly from the rear portion of a slide 376 (Fig. 10) mounted in a suitable guideway in a horizontal plate 378 fixed to the bracket 55 352. The forward portion of the slide 376 is provided with rack teeth which mesh with a spur gear 380 freely mounted on a fixed shaft 382 and arranged to mesh with an idle gear 384 freely mounted on a fixed shaft 386 and arranged to mesh with rack teeth formed in the 60 65 70 75

lower portion of a vertical shaft 388 mounted for sliding movement in suitable bearings in the machine frame. Referring to Fig. 1, the upper portion of the sliding shaft 388 is provided with rack teeth which mesh with a gear 390 fixed to the right end portion of the shaft 366 projecting outwardly from the standard 136 at the right side of the machine.

In handling the first counter to be operated on in any period of operation of the machine the counter carrier is advanced manually from its loading position into counter immersing position and back to its loading position to permit the counter to drain thus obviating the necessity of putting the machine through the main cycle of operations for the sole purpose of applying adhesive to the counter. Inasmuch as the shaft 366 is not manually operable the manual operation of the counter carrier involves angular movement of the counter carrier relatively to the shaft 366. To this end the stem 392 (Fig. 34) at the extremity of the counter carrier is bifurcated, as shown in Fig. 15, to receive an ear 394 extending laterally from a hub 396. The bifurcated end portion of the counter carrier is pivotally connected to the ear 394 by a cross pin 398. The assembly comprising the bifurcated end portion of the carrier, the ear 394, and the pin 398 are shaped to present a cylindrical contour of predetermined diameter to the cylindrical inner surface of a collar 400 of substantially the same diameter. In its normal position illustrated in Fig. 15 the collar surrounds the assembly above referred to and holds the counter carrier against swinging movement relatively to the hub 396. When it is desired to swing the counter carrier on the pin 398 the collar is moved away from the hub against the pressure of a spring 402 surrounding the stem 392 and serving to hold the collar in its position in Fig. 15. To facilitate such manual movement of the collar it is provided with a peripheral flange 404.

The illustrated counter carrier comprises a U-shaped frame member 406 (Fig. 15) fixed to the stem 392 and a counter holder pivotally mounted on two headed screws 408 mounted in the upper end portions respectively of the frame member. For reasons which will hereinafter appear the end portions of the frame member are curved, as shown in Fig. 13, so that the screws 408 which mount the counter holder are offset laterally from the center lines of the body portions of the arms of the frame member. The counter holder comprises two like plates 410 of irregular outline arranged in parallel relation to each other and in contiguous relation to the outer surfaces of the frame member 406. As shown in Fig. 16, the plates 410 are connected together by a cross head 412 located at the end portions of the plates which are uppermost, as seen in Fig. 17. For mounting a molded counter on the holder each of the plates 410 has a flange or a foot 414 projecting outwardly therefrom. As shown in Fig. 16, the two feet are so constructed that together they provide suitable means for supporting the rear portion of an upstanding counter by its flange. Cooperating with each of the feet 414 is a spring clip 416 secured to the plate 410 and arranged to overlie the upper surface of the foot 414, the clip being spaced from the foot a distance corresponding approximately to the thickness of the flange of a counter. In order to hold the counter against dislocation on the holder during the movements of the counter carrier, each plate 410 has mounted in a suitable socket, a spring pressed pin 418 (Fig. 17) the pointed end of which projects slightly above the foot 414 for gripping engagement with the flange of the counter.

During the movement of the counter carrier from its counter draining position shown in Fig. 34 into its position shown in Fig. 43 in which it supports the counter in the heel end portion of a shoe upper in the machine the counter holder swings in a counterclockwise direction, as seen in Fig. 13, about the two screws 408 mounted in the two arms of the U-shaped frame 406. Such

swinging movement of the counter holder operates in conjunction with the angular movement of the frame member 406 to bring the counter into proper orientation relatively to the supported upper at the end of the counter inserting movement of the counter carrier assembly. When the counter carrier is in its counter draining position the plates 410 of the counter holder are yieldingly held against counterclockwise movement from their angular position relatively to the frame member 406 illustrated in Fig. 34 by a ball latch indicated generally by the numeral 420 and when the counter carrier is in its position shown in Fig. 43 with the counter mounted in the supported upper the plates 410 of the counter holder are yieldingly held in their angular relation to the frame member 406 illustrated in Fig. 43 by a ball latch indicated generally by the numeral 422. Referring to Fig. 18, the latch 422 comprises a ball 424 mounted in a bore extending through the plate 410 and through a boss 426 projecting outwardly from the plate. The ball 424 is normally seated against the convergent surface of the reduced inner end portion of the bore by a spring 428 mounted in the bore and confined between the ball and a screw plug 430 mounted in a tapped counter bore in the boss 426. The construction and arrangement of the ball latch 420 is the same as the ball latch 422 and will be understood from the foregoing description. It will be understood that the illustrated counter carrier assembly is provided with four ball latches of the type illustrated in Fig. 18, two on each of the plates 410. The ball latch illustrated in Fig. 18, this being one of the two ball latches in the plate 410 at the right side of the counter carrier, operates in a rounded socket 432 formed in the member 406. The ball latch 420 also operates in the socket 432 to maintain the counter holder in its position in Fig. 34.

In order to hold the counter carrier against angular misplacement during the transfer of a counter from the conveyor to the carrier the illustrated machine is provided with means for positively holding the counter mounting assembly against clockwise movement upon the frame member 406 (Fig. 13). To this end the frame member 406 has a projection 433 which provides a stop for two pins 435 carried by the plates 410, respectively (Fig. 15).

The swinging movement of the counter holder during the operation of the counter carrier is caused by stationary cam plates fixed to the inner surfaces of the standards 136. Referring to Fig. 34, illustrating the cam plates on the standard 136 at the left side of the machine, an upper cam plate 434 is located in predetermined relation to the standard 136 by two dowel pins 436 and is attached to the standard by screws 438. A lower cam plate 440 is located in predetermined relation to the standard 136 by two dowel pins 442 and is secured to the standard by screws 444. The two cam plates are located in a spaced relation to each other such that the angular lower edge face of the plate 434 forms the upper wall of a cam groove 446 and the angular upper edge face of the plate 440 forms the lower wall of the cam groove. During the movement of the counter carrier in a counterclockwise direction, as seen in Fig. 34, two rolls carried by the counter holder enter the rear ends of the cam groove 446 and the corresponding cam groove in the standard 136 at the right side of the machine. The advancement of the rolls forwardly through the cam grooves causes the counter holder to swing approximately 100° in a counterclockwise direction about the screws 408 in the member 406. Such angular movement of the counter holder advances the ball latch 422 into latching position and during the remainder of the counterclockwise movement of the counter carrier the angular disposition of the counter holder to the member 406 is maintained by the ball latch 422 and the corresponding latch at the opposite side of the counter holder. Referring to Fig. 16, the two cam rolls carried by the counter holder are

identified by the numeral 448. The rolls are pivotally mounted at the outer ends of two aligned stems 450 extending perpendicularly in opposite directions from the plates 410.

In order to facilitate the operation of the wipers which upwipe the quarter lining the wings of the counter are outspread into their position illustrated in broken lines in Fig. 59 by the operation of two spreader pins 452 carried by the counter holder. Referring to Fig. 15, the spreader pins are mounted on arcuate arms 454 projecting respectively from hubs 456. Referring to Fig. 17, the hub 456 at the right side of the counter carrier is slidably mounted on a shaft 458 and held against rotation thereon by a pin 460 mounted in the hub and extending into a splineway 462 in the shaft 458. The shaft 458 is mounted to rotate in bearings in ears 464 and 466 projecting outwardly from the plate 410. The shaft is held against endwise movement in its bearings by an end plate 468 at the upper end of the shaft as seen in Fig. 17 and a hub 470 fixed to the lower end of the shaft. As shown in Fig. 16, the spreader pins 452 are fixed in cylindrical bosses 472 projecting from the arms 454, the spreader pins extending in the direction of the counter 364 on the carrier from the bosses on the arms. The spreader pins remain in their inoperative position shown in Fig. 16 until the counter carrier approaches the end of its counter inserting movement. During the latter part of such movement and after the counter has entered the shoe upper in the machine the spreader pins receive equal and opposite movement away from each other to spread the wings of the counter into their position indicated in Fig. 59. The spreader pins are yieldingly held in their position illustrated in Fig. 16 by the action of torsion springs one of which is illustrated in Fig. 17 and identified by the numeral 474. At its upper end the spring 474 is anchored to the hub 456 of the arm 454 and at its lower end the torsion spring is anchored to the ear 466. For imparting to the spreader pins equal and opposite movement away from each other to outspread the counter wings the illustrated machine is provided with two cam members mounted on the inner surfaces of the standards 136, one of said cam members being illustrated in Fig. 13 and identified by the numeral 476. The cam 476 is an arcuate plate pivotally mounted at its upper end on the standard 136 and arranged to engage a detent 478 located adjacent to the free end of the cam member and slidably mounted between the standard 136 and a grooved plate 480 fixed to the inner surface of the standard. The cam plate is urged in a clockwise direction, as seen in Fig. 13, against the detent 478 by a spring 482 anchored at one end to a pin projecting outwardly from the standard 136 and at its opposite end to an arm 484 extending radially from a hub 486 of the cam member projecting outwardly through a bore in the standard. During the counterclockwise swinging movement of the counter carrier assembly the cam 476 is engaged by a pin 488 projecting perpendicularly from the enlarged left end portion of a rod 490 slidably mounted in a bearing in a bracket 492 fixed to the lower end portion of the plate 410. During the latter part of the counterclockwise swinging movement of the counter carrier assembly the counter-holder is in its position in front of the standards 136 illustrated in broken lines in Fig. 13 and the pin 488 engages the concave rear surface of the cam member 476 causing the rod 490 to slide rearwardly or to the right as seen in Fig. 13. Referring to Figs. 16 and 17 the reduced end portion of the rod 490 is pivotally connected to a short arm 494 (Fig. 16) projecting outwardly from the hub 470. Thus it will be seen that the rearward movement of the sliding rod 490 rotates the shaft 458 in a direction to actuate the spreader pin 452. During the upwiping operation of the lining wiper assembly a plate at the upper extremity of the lining wiper assembly engages pins 496 (Fig. 16) extending downwardly from the free end portions of the arms 454 and moves the spreader assemblies upwardly against the expansive force

of the spring 474 (Fig. 17) and a like spring at the opposite side of the counter carrier assembly. When the arm 454 has moved endwise of the shaft 458 into its position illustrated in Fig. 17 the spring 474 swings the arm 454 into a position in which a shelf 498 (Fig. 16) on the boss 472 moves in underneath a shoulder 500 (Fig. 17) on the plate 410 thereby to hold the arm 454 against return movement. During the latter part of the upwiping movement of the lining wiper assembly, mechanism hereinafter described is operated to retract the detent 478 thus permitting the spring 482 to swing the cam 476 into its inoperative position illustrated by broken lines in Fig. 13. Thereupon the torsion spring 474 and the corresponding spring at the opposite side of the counter holder swings the arms 454 toward each other to return the spreader pins 452 to their inoperative position shown in Fig. 16 thus permitting the counter to close by its inherent resiliency. The retraction of the detent 478 occurs just before the lining wipers come to the limit of their upwiping movement and just before the shelf 498 on each boss 472 comes into position to engage the shoulder 500 on the plate 410. Referring to Fig. 13, during the counterclockwise movement of the counter carrier assembly and at the time when the counter holder is passing through its intermediate position in front of the standards 136 illustrated by broken lines in Fig. 13 mechanism now to be described swings the arms 454 just far enough to disengage the shelf 498 on each of the bosses 472 from the shoulder 500 in order to permit the spreader pins to be moved endwise of the shafts 458 into position for the next counter spreading operation. Referring to Fig. 20, a bracket 502 fixed to the standard 136 has a pin 504 extending downwardly therefrom into the path of movement of a cam member 506 pivotally mounted in an opening rectilinear in cross section formed in an outward extension 508 of the arm 454. The cam member is yieldingly held in its position illustrated in Fig. 20 by a spring 510 mounted in a socket in the arm 454 and arranged to bear against the cam member. During the counter inserting movement of the counter carrier a cam surface 512 (Fig. 21) in the cam member 506 engages the pin 504 and swings the arm 454 in the direction of the arrow in Fig. 17 thereby to disengage the shelf 498 (Fig. 16) from the shoulder 500 to permit the spring 474 to advance the spreader pin at the right side of the counter holder. Mechanism similar to that above described operates to disengage the boss 472 at the left side of the counter holder from the shoulder in the left plate 410. At an early stage in the return movement of the counter carrier the pin 488 in the rod 490 engages a detent 491 (Fig. 13) pivotally mounted on the headed screw 493 mounted in the cam member 476 and normally held in its position illustrated in Fig. 13 by a spring 495, this position being determined by the engagement of the upper edge face of the detent with a shoulder 497 formed in the upper end portion of the cam member. The upper end of the spring 495 is connected to a stem 499 projecting radially from the detent and the lower end of the spring is anchored to a pin 501 mounted in the cam member. The pin 488, during its upward movement from its position illustrated in Fig. 13, engages the detent 491 and swings the cam member 476 in a counterclockwise direction, as seen in Fig. 13, to return the cam member to its full line position in which it is maintained by the detent 478. During the downward movement of the pin 488 the detent 491 swings idly in a clockwise direction, as seen in Fig. 13, as the pin passes through the position occupied by the detent and the spring 495 returns the detent to its normal position after the pin 488 is moved beyond it. During the clockwise or return movement of the counter carrier the surface 514 (Fig. 21) of the cam member 506 engages the pin 504 and swings the cam member idly to the right as the counter assembly passes the pin. In order to permit limited adjustment of the position heightwise of the upper in which the counter is located by the counter carrier a cam plate 516 (Fig. 19) is slidably mounted in

a groove 518 formed in the upper surface of the cam 370 and extending generally radially thereof. The groove 518 communicates with the cam groove 372 and the inner end face of the plate 516 forms a portion of the outer wall of the cam groove. The plate 516 is adjustable in the groove 518 to vary slightly the path of movement of the cam roll, the plate being secured in adjusted position by a clamping screw 520 extending through a longitudinal slot 522 in the plate 516 and into a tapped hole in the cam 370. For positioning the heel form 166 heightwise of a shoe upper in the machine, preparatory to the wiping and tacking operations, the counter holder is provided with two abutment screws 524 (Figs. 16 and 17). Referring to Fig. 101, the abutment screws are so arranged that the upward movement of the heel form in the course of the operation of the machine brings an insole 526 mounted on the heel form into engagement with the abutment screws thereby to determine the position of the heel form and the insole thereon heightwise of the supported upper when the heel form is at the limit of its advancement into the supported upper. It will be understood from an examination of the drawings, e.g. Figs. 100 and 101, that the illustrated heel form 166 is constructed to support a loose insole, that is, an insole which has not been attached to a last bottom. Referring to Fig. 17, each abutment screw 524 is mounted in a tapped hole in a flange 528 projecting outwardly from the upper end portion of the plate 410, as seen in Fig. 16, the flange being provided with a rounded extension in which the abutment screw is mounted. The abutment screws are adjustable in the flange 528 and are secured in adjusted position by lock nuts 530.

In order to position the counter holder lengthwise of a shoe upper supported in the machine a bracket 650 (Fig. 13) is secured to the left standard 136 and has mounted therein an abutment screw 652 which, as shown in Fig. 13, is constructed and arranged to engage an angular extension 654 (Fig. 17) of the bracket 492 on the left plate 410 of the counter holder as the holder comes to the limit of its counter inserting movement. As shown in Fig. 14, an abutment screw 656 mounted in a bracket 658 acts against an angular extension 660 of the bracket 492 on the plate 410 at the right side of the counter holder.

Referring to Figs. 23 and 24, the illustrated machine is provided with a counter conveyor mechanism comprising parallel vertical plates 542 forming the side walls of a frame mechanism. The plates 542 are spaced apart from each other and are interconnected at their upper and lower extremities by cross bars 543 secured to rearward extensions 545 of the plates. For mounting a plurality of counters a carrier herein illustrated as a chain 532 is mounted between the plates 542 on a lower sprocket 534 (Fig. 22) and an upper sprocket 536. The lower sprocket 534 is fixed to a shaft 538 the right end of which is mounted in a bearing in a journal member 541 (Fig. 28) slidably mounted in a guideway in the plate 542 at the right side of the conveyor assembly. The left end portion of the shaft 538 is mounted in a bearing in a journal member 540 similar to the journal member 541 and slidably mounted in a guideway in the plate 542 at the left side of the conveyor assembly. The upper sprocket 536 is secured to a shaft 544 mounted in bearings in aligned bosses 546 extending inwardly from the plates 542 at the upper extremity thereof. Referring to Fig. 26, the chain 532 comprises two trains of flat links spaced apart from each other widthwise of the chain, the links being connected together by cross pins 548. The two trains of links are spaced apart from each other sufficiently to provide for the attachment, to each pair of links, of a plate 550 having formed therein a boss 552 having a peripheral contour corresponding substantially to the shape of the top edge at the rear portion of a molded counter. Each plate 550 has a pair of ears 554 arranged perpendicular thereto and in contiguous

relation to the inner surfaces of the links. For engaging the outer surface of the rear portion of the counter each pair of links has secured to its outer surface a pair of resiliently flexible arms 556 the inner surfaces of which are contoured to conform to the outer surfaces of the counter at opposite sides of its back line. The ears 554 and the arms 556 are attached together with the links therebetween by headed screws 558 extending through bores in the arm and the links and into tapped holes in the ears. Mounted in each of the bosses 552 and projecting upwardly from its upper extremity, as seen in Fig. 26, is a sharp pointed pin 560 projecting upwardly from a rod 562 slidably mounted in a counter bore communicating at its upper end with a bore through which extends the pin 560. Upward pressure is applied to the rod 562 by a spring 564 mounted in the counterbore and confined between the base of the rod and a screw plug at the lower extremity of the counter bore. Referring to Fig. 22, the housing is secured by screws 566 to the slide 146. Referring to Figs. 22 and 25, the counters on the chain 532 are held against misplacement during the operation of the chain by a pair of retainer plates or rails 568 hinged at the forward extremities of plates 570 secured to, and extending forwardly from, the plates 542. The retainer plates are normally held in engagement with the opposite end portions of the counter flanges by the tension of a light spring 572 which, as shown in Fig. 25, is anchored at one end thereof to the free end of an arm 574 secured to a hinge pin 576 to which the left plate 568 is secured and anchored at its opposite end to a hinge pin 578 to which the right plate 568 is secured. The tension of the spring 572 is imparted to the right plate 568 by a link 580 connecting the free end of the arm 574 to the free end of an arm 582 secured to and extending rearwardly and outwardly from the upper end of the right hinge pin 578. In order to facilitate the mounting of counters on the conveyor, the retainer plates 568 are held in their open position, shown in Fig. 24, by an eccentric button 584 mounted for turning movement in the left plate 570 and provided with a knurled head 586 to facilitate such turning movement. As shown in Fig. 27, the eccentric button 584 engages an arm 588 which extends rearwardly from the left retainer plate 568 when the plate is in its open position shown in Fig. 24. During the operation of the counter carrier the counter conveyor is elevated into its position shown in Fig. 22 to provide clearance for the movement of the counter by the carrier. At the appropriate time in the main cycle of the machine the counter in the leading station in the conveyor, that is the lowermost counter on the chain 532 (Fig. 30) is mounted on the counter holder by first moving the slide 146 downwardly into a loading station relatively to the counter carrier (Fig. 31) and then advancing the chain downwardly by an indexing movement to insert the flange of the lowermost counter between the flange engaging members of the counter holder. At the end of the downward movement of the slide 146 the lowermost counter on the chain 532 is in the position relatively to the counter holder illustrated in Figs. 31 and 33, the counter holder at this time being in its loading station illustrated in Fig. 13 by the broken line showing of the counter holder at the rear of the standards 136. During the indexing movement of the chain 532 the flange of the counter is inserted between the feet 414 and the clips 416 of the counter holder and is advanced into a position in which the pins 418 engage the flange of the counter to hold it in the relation to the counter holder effected by the advancement of the edge of the counter flange with a shoulder 590 formed in the feet 414. During the latter part of the indexing movement of the chain the arms 556 spring outwardly and move out of engagement with the counter and thereupon the slide 146 moves upwardly to return the conveyor assembly to its elevated position. As

shown in Figs. 30 to 32 the counters on the conveyor are in contact with the retainer plates 568 during the downward movement of the counters and the retainer plates are located in predetermined relation to the counter holder in its loading station such that the flange of the counter registers accurately with the space between the feet 414 and the clips 416 of the counter holder as the counter moves downwardly into its loading position shown in Figs. 31 and 32. In the illustrated organization the retainer plates 568 are located in predetermined counter engaging position by lugs 592 (Fig. 25) extending inwardly from the plates 570. Inasmuch as counter heights vary in proportion to counter sizes, the lower portion of the counter conveyor is constructed and arranged for self adjustment heightwise of the counters thereon in order to insure the engagement of the counter flanges with the retainer plates 568. In the illustrated organization such self adjustment is effected by springs 594 (Figs. 24 and 28) mounted in sockets in the plates 542 and arranged to engage the journal members 540 and 541 and urge them in a direction to maintain contact of the counter flanges with the retainer plates. Referring to Fig. 35 the slide 146 is actuated to impart upward movement to the counter conveyor assembly by a cam 596 fixed to the cam shaft 172 and arranged to engage a roll 598 pivotally mounted on a lever 600 mounted to swing on a fixed fulcrum 602. The lever 600 is connected by a link 604 to a lever 606 mounted to swing on a fixed fulcrum 608, the lever 606 being connected to the slide 146 by a link 610. In order to provide for adjustment of the position of the counter conveyor assembly at the limit of its downward movement the link 604 is adjustable lengthwise of the lever 606 within the limits of a slot 612 formed in the lever. In the illustrated organization downward movement of the conveyor assembly is effected by gravity aided by a spring 613 acting on the lever 606 and is governed by the cam 596. The indexing movement of the counter carrying chain 532 is effected by the operation of a cam 614 fixed to the cam shaft 172 and arranged to engage a roll 616 mounted on a lever 618 which swings on a fixed fulcrum 620. Pivoted on the free end of the lever 618 is an extensible link 622 having a universal connection at its upper end with the rounded head of a pin 624 (Fig. 38) projecting from a clutch member or block 626. Referring to Fig. 37, the clutch block is pivotally mounted between ears 628 projecting from opposite sides of a channel member 630 and arranged for clutching engagement with a slide 632 mounted for vertical movement in the channel member. The channel member 630 is slidably mounted in a channel member 634 fixed to the machine frame and the slide 632, together with the channel member 630, are retained in their position relatively to each other and relatively to the channel member 634, shown in Fig. 37, by gibs 636 (Fig. 36) fixed to the channel member 634. The slide 632 is connected to the indexing mechanism by a link 638 the lower end of which carries a head 640 which is pivotally connected to the upper extremity of the slide 632. In order to permit free sliding movement of the slide 632 in the channel member 630 during the operation of the slide 146 the clutch block 626 is normally held out of clutching engagement with the slide 632 by a spring 642 anchored at its lower end to the clutch block and at its upper end on a fixed member 644. In the illustrated organization the spring 642 also serves to maintain contact between the roll 616 and the cam 614. Referring to Figs. 36 and 38, the normal position of the clutch block is determined by its engagement with an abutment screw 646 mounted in a crosshead 648 extending between the ears 628. During the operation of the cam 614 the clutch block 626 is swung in a counterclockwise direction, as seen in Figs. 35 and 38, to bring it into clutching engagement with the slide 632 and thereafter the cam imparts downward movement to the slide 632 and

the channel member 630 as a unit to actuate the indexing mechanism. Referring to Fig. 23, the indexing mechanism comprises a pawl carrier or plate 662 mounted to swing freely on the shaft 538 and having pivotally mounted at its free end portion a head 664 at the upper end of the link 638. Pivotally mounted on a pin in an upward extension of the plate 662 is a pawl 666 which is urged by a spring 668 on the plate 662 into engagement with a ratchet wheel 670 fixed to the shaft 538. The downward movement of the link 638 turns the ratchet wheel 670 40° in a counterclockwise direction as seen in Fig. 23 to advance the sprocket 534 to the extent of the angular displacement between adjacent teeth on the sprocket 534. The plate 662 is swung in a clockwise direction into its rest position by the operation of a spring 672 the upper end of which is anchored to an arm 674 projecting radially to the right, as seen in Fig. 23, from the hub of the plate 662 and at its lower end to a pin on the plate 542. The rest position of the plate 662 is accurately determined by an abutment screw 676 mounted in a boss 678 on the plate 542 and arranged to arrest the swinging movement of the arm 674. During the clockwise movement of the plate 662 the ratchet wheel 670 is held against clockwise movement by a detent 680 pivotally mounted on the plate 542. To facilitate and expedite the mounting of a plurality of counters on the counter conveyor the present invention contemplates the provision of a container or box such as that illustrated in Fig. 39 for mounting a plurality of counters in the same spaced relation in which they are located on the conveyor, as shown in Fig. 22. The illustrated box has two side walls 682, two end walls 684 and a bottom comprising two side plates 686 and a center plate 688 spaced from the two side plates. The center plate 688 has bosses projecting upwardly therefrom one of said bosses being identified by the numeral 690. The bosses are spaced apart from each other lengthwise of the box to the same extent as the bosses 552 on the conveyor chain, illustrated in Fig. 27. As shown in Fig. 39, each of the bosses has a flat face extending widthwise of the box and perpendicular to the center plate 688 and a convex face having a curvature substantially complementary to the curvature of the edge of the counter flange at the back line of the counter. As shown in Fig. 42, each boss has at its base a groove 692 which receives the flange of the counter and holds the counter against inadvertent displacement in the box. Each boss is slabbed off angularly forwardly of its convex surface, as indicated at 694 in Fig. 42, the slabbed off surface having a curvature conforming substantially to the convex curvature of the curved surface of the boss. As shown in Fig. 42, the slabbed off surface receives the outer surface of that portion of the back line region of the counter adjacent to the counter flange in the positioning of the counter within the box. Referring to Fig. 39, the wings of each counter in the box are located in predetermined spaced relation to each other by pins projecting perpendicularly from the side plates 686 and engaging the edge of the counter flange, two such pins being identified in Fig. 39 by the numeral 696. In presenting the box of counters to the counter conveyor the box is arranged in upright position, as shown in Fig. 40, with the bottom of the box facing the operator and the wings of the counters pointing downward. The retainer plates 568 are swung into their open position shown in Fig. 24 in order to admit the box into the space between the plates 570. In order to determine accurately the vertical position of the box with relation to the counter conveyor, each plate 570 has a shelf 698 extending inwardly therefrom at the lower end portions of the plates 570. The two shelves support the box by its then lower end wall 684 and so position the box with relation to the conveyor that the counters in the box are so arranged that a light pressure of the fingers of the operator applied to the flanges of the counters through the spaces in the bottom of the box dislodge the counters

from the box and move them rearwardly into a predetermined relation to the conveyor such that each counter is mounted on a block 552 (Fig. 26) and its rear portion is positioned between a pair of arms 556, as shown in Fig. 24. After each counter in the box has been advanced rearwardly into registration with the boss 552, downward pressure is applied to the counter to cause it to be impaled upon the pin 560 projecting upwardly from the boss. This is all accomplished quickly and easily by the downward movement of two fingers through the longitudinal openings in the bottom of the box.

For wiping the back line portion of the quarter lining heightwise from the top line of the upper to the flange of the counter, thereby to cause the lining to adhere to the cement treated inner surface of the counter, the illustrated machine is provided with a pair of lining wiper plates 700 (Fig. 43) which are moved upwardly from their full line position, shown in said figure, to the uppermost of four broken line positions by the depression of the treadle 200 (Fig. 1). The lining wiper plates 700 are carried by a T-head 702 mounted in a groove in the rearwardly curved upper end portion of a slide 704 and adjustably secured therein by a clamping screw 706. The slide 704 is mounted for generally vertical movement in grooves in the mutually adjacent surfaces of two parallel vertical arms one of which is illustrated in Figs. 1, 43 and 46 and identified by the numeral 708. As shown in Fig. 1, the vertical arms are pivotally mounted at their lower ends for forward and rearward swinging movement on a fixed cross pin 710. For imparting upward movement to the slide 704 a link 712 is pivotally mounted at its lower end on the treadle 200 and at its upper end in the forwardly offset lower portion of a slide 714 which, as shown in Fig. 43, is mounted in a vertical groove 716 in a plate 718 fixed to the right arm 708. Rack teeth formed in the upper portion of the slide 714 mesh with a pinion 720 positioned in a recess in the plate 718 and fixed to a stud 722 mounted to rotate in the plate 718 and in a boss 724 (Fig. 46) formed in a cover plate 726. The movement of the slide 714 is transmitted through the pinion to a rack 728 slidably mounted in a groove 730 formed in the plate 718. The upper portion of the rack 728 is forwardly offset and connected to the slide 704 by a headed screw 732 extending through a slot 734 in the right arm 708 and into the slide. Referring to Fig. 54, the illustrated lining wiper plates 700 are connected together at their rear ends by a halved joint 736 for expanding and contracting movement and are normally held in their contracted position, shown in Fig. 54, by a tension spring 738. The wiping portions of the lining wiper plates comprise upwardly extending flanges 740 extending along the outer periphery of said plates from the halved joint to points midway between the front and the back of the wiper assembly. To provide for the mounting of the wiper assembly the forward portion of each plate has a rectilinear inner edge 742 extending rearwardly from the forward end of the wiper plate and rabbed for engagement with a flanged member 744 (Fig. 51) when the wiper plate is in its closed position shown in Fig. 51. The flanged member 744 is fixed to the upper surface of the T-head 702. To provide space for the spring 738 the upper surface of the T-head has formed therein a recess illustrated in Fig. 53 having a straight rear wall 746 and an angular forward wall 748. In the operation of the lining wipers the slide 704 moves rearwardly or to the right, as seen in Fig. 43, by swinging movement of the assembly on the cross pin 710 (Fig. 1) to bring the wiping edges at the rear ends of the wiper plates into engagement with the quarter lining under yielding pressure. The pressure of the wiper plates against the lining causes a relative movement of the wiper plates and the T-head 702 which causes the convex edge faces 750 formed in the wiper plates respectively to engage fingers 752 (Fig. 53) formed in the flanged member 744, thereby camming the wiper plates outwardly into

lining engaging position. Upon the completion of their wiping movement the wipers are returned to their contracted position by the spring 738. For holding the lining wiper plates against upward movement a top plate 754 (Fig. 56) is mounted on the upper surface of the flanged member 744, shown in Fig. 50, and the plate and the member are secured together to the T-head 702 by headed screws 756. Fixed to each side portion of the top plate 754 and projecting upwardly therefrom are blades 758 (Fig. 48) which cooperate with the counter spreading rods 452 (Fig. 52) to guide the opposite side portions of the quarter lining upwardly into the jaws of the breast line lining grippers. As shown in Fig. 48, the blades 758 are positioned forwardly of the wiping flanges of the lining wiper plates and therefore operate on portions of the lining which are not brought into intimate contact with the counter during the lining wiping operation but remain inwardly spaced from the counter, as shown in Fig. 58. During the upward movement of the lining wiper assembly outward extensions 760 of the top plate 754, shown in Fig. 49, engage the bottom ends of the pins 496 (Fig. 52) thereby to move the counter spreader assembly upwardly into a position in which it is out of contact with the counter thus permitting the counter wings to close 25 to their normal position by their inherent resiliency. The counter spreading assembly is retained in its elevated position by the engagement of the shelf 498 (Figs. 16 and 17) with the shoulder 500 in the counter holder.

For applying wiping pressure to the lining wipers a 30 spring pressed roll 762 (Fig. 43) is constructed and arranged to engage the forward edge face of a cam plate 764 fixed to the slide 704. Referring to Fig. 47, the roll 762 is pivotally mounted in the bifurcated rear end portion of a bar 766 mounted for sliding movement in a 35 guideway in a member 768 and is yieldingly urged to the right, as seen in said figure, by a spring 770 mounted in a socket formed in said bar. Referring to Fig. 45, the member 768 has flanges 772 and 774 projecting respectively upwardly and downwardly from the right side portion of said member and arranged to be engaged by gib 776 fixed to a plate 778 and arranged to retain the flanged portion of said member in a groove 780 formed in said plate. The plate 778 is adjustably secured to a plate 782 by screws 784 and the plate 782 is secured by screws 45 786 (Fig. 43) to a plate 788 fixed to a rail 790 secured to and extending forwardly from the machine table 130. The member 768 is urged to the right, as seen in Fig. 43, by a spring 792 the left end of which is anchored to the member 768 and the right end to the lower gib 776. A 50 leaf spring 794 fixed to the upper surface of the plate 778 bears against the forward end of the member 768 urging it downwardly against the base of the groove 780 and urging its rear end upwardly against the top of the groove, as shown in Fig. 43. When the member 768 is in this position an ear 796 projecting upwardly from its rear end engages the end face of the plate 778 and positively holds the member 768 against forward movement. During the upward movement of the lining wiping assembly the member 768 is in its position shown in Fig. 55 60 43 and forward movement of the roll 762 is resisted by the relatively heavy spring 770 (Fig. 47) and the spring 792 is inactive. During the upward movement of the lining wiper assembly the roll 762 bears against the forward edge of the cam plate 764. The lower portion of 65 the cam plate 764 is so constructed and arranged that the bar 766, which carries the roll 762, is moved slightly to the left during the upward movement of the wiper assembly causing the spring 770 to apply wiping pressure to the lining wipers. During the downward movement of the 70 wiper assembly the cam plate 764 moves the roll 762 downwardly disengaging the ear 796 from the end face of the plate 778 and permitting the member 768 to move to the left, as seen in Fig. 43, against the tension of the light spring 792 thus permitting the wiper assembly to 75 move downwardly without danger of dislocating the up-

wiped quarter lining. At an early stage in the downward movement of the wiper assembly the lining wipers are moved forwardly away from the lining by the engagement of a plate 798 fixed to the slide 704 with a roll 800 mounted at the forward end of a slide 802 mounted in a groove 804 formed in a plate 806 fixed to a vertical plate 808 secured at its upper end to the rail 790. The walls of the groove 804 converge rearwardly thus permitting a vertical swinging movement of the slide 802, said slide being retained within the groove by gibs 810 fixed to the plate 806. The slide 802 is urged forwardly by a spring 812 the rear end of which is anchored to the slide and the forward end to the upper gib 810. The slide 802 is normally in its rest position, shown in Fig. 43, in which a notch formed in the lower portion of the slide registers with a lug 814 formed in the plate 806 to hold the slide positively against rearward movement. During the upward movement of the lining wiper assembly the cam plate 798 engages the roll 800 and moves the slide 802 upwardly disengaging it from the lug 814 and thus freeing it for rearward movement against the light spring 812 which offers no appreciable resistance to the rearward movement of the wiper assembly by the spring 770 (Fig. 47). During the downward movement of the wiper assembly the cam plate 798 swings the slide 802 downwardly into its position shown in Fig. 43 in which the slide is positively held against rearward movement by the lug 814. During the continued downward movement of the wiper assembly the roll 800 acting on the cam plate 798 moves the lining wipers forwardly out of engagement with the lining and holds them out of engagement with the lining as they move downwardly out of the upper.

During the upward movement of the lining wipers the detent 478 (Fig. 13) is retracted by mechanism actuated by the lining wiper treadle 200 to permit the retraction of the cam member 476 into its rest position, indicated by broken lines in Fig. 13, and a like detent in the standard 136 at the right side is similarly retracted to permit the release of a similar cam member in the right standard. The release of the cam members permits the return of the counter spreading pins 452 to their retracted positions. As shown in Fig. 1, the mechanism for retracting the detent 478 comprises an arm 832 pivotally mounted at its lower end on the lining wiper treadle 200 and normally held in its position shown in Fig. 1 by a spring 834 which urges the arm forwardly against a stop pin 836 mounted in the treadle. The arm 832 is held against sidesway by a fixed plate 833 (Fig. 78) which is slotted to receive the arm. The arm 832 carries at its upper end a detent 830 (Fig. 76) constructed and arranged to engage the reduced end portion of a plate 838 at an early stage in the upward or return movement of the treadle. The plate 838 is adjustably mounted in a groove 839 in an arm 840 fixed to a cross shaft 842 mounted in bearings in two brackets 844 (Fig. 75) fixed to and extending forwardly from the forward legs 132 and 134, respectively. Upward movement of the free end of the plate 838 rotates the shaft 842 in a counterclockwise direction, as seen in Fig. 76. Referring to Figs. 75 and 77, an arm 864 fixed to the shaft 842, is connected by a long link 816 to the horizontal arm of a bell crank lever 818 (Fig. 13) having a fixed fulcrum 820 on the standard 136 at the left side of the counter carrier assembly. The vertical arm of the bell crank lever has a pin-and-slot connection to the rear end of a link 822 the forward end of which is pivoted to the vertical arm of a bell crank lever 824 having a fixed fulcrum 826 on the left standard 136. The horizontal arm of the bell crank lever 824 is slotted to receive a pin 828 mounted in the detent 478 and extending outwardly through a slot in the left standard 136. The pin-and-slot connection between the bell crank lever 818 and the link 822 permits the detent 478 to move freely when the lining wiper treadle is elevated thus permitting the return of the cam member 476 from its broken line posi-

tion in Fig. 13 to its full line position by the manual operation of the arm 484.

The rotation of the shaft 842 by the upward movement of the lining wiper treadle operates through mechanism now to be described to release the breast line gripper jaws for closing movement to their positions shown in Fig. 73. The rotation of the shaft 842 imparts downward movement to two arms 846 and 848 secured to the opposite end portions of the shaft 842 and pivotally connected, respectively, to the lower ends of links 850 and 852. The upper end portion of the link 850 is slidably mounted in the horizontal upper end portion of a bracket 854 secured to the machine table 130. At its upper end the link 850 has fixed thereto an arm 856 which acts against the free end of an arm 858 during the downward movement of the link to release the latches in the breast line grippers at the right side of the shoe. For releasing the latches in the breast line grippers at the left side of the shoe the link 852 carries at its upper end an arm 860 which actuates an arm 862. The construction and operation of the arms 858 and 862 in their respective breast line gripper assemblies is hereinafter described.

The top marginal portion of a lined upper mounted in the machine is positioned for the lining wiping operation by four top line pads, two at each side of the machine, the forward pads being identified by the numeral 866 and the rear pads by the numeral 868 (Figs. 88 and 89). The top line pads move into engagement with the top marginal portion at opposite sides of the heel end of the upper at an early stage in the upward movement of the lining wipers and thereby bring the upper into intimate contact with the outer surface of the counter in the counter holder under light spring pressure. The marginal portion of the upper extending heightwise beyond the edge of the counter is urged inwardly by the top line pads as shown in Fig. 52 under light spring pressure, thus bringing the top margin into a position in which it is in alignment with the counter wings heightwise thereof. Such positioning of the top margin by the top line pads insures the most desirable relation between the lining and the counter for the lining wiping operation. The illustrated top line pad assemblies are substantially alike, and the construction and operation of both assemblies will be understood from the following description of the right-hand assembly which is illustrated in detail in Figs. 88 to 91. The forward pad 866 is fixed to a rigid backing plate 870 which is mounted for limited angular movement at one end of a bent slide 872, said backing plate having a central boss 874 which is recessed to receive the end portion of the slide on which it is pivotally mounted. Similarly, the rear pad 868 is fixed to a rigid backing plate 876 which is mounted for limited angular movement on a slide 878 in the same manner as the backing plate 870. The slides 872 and 878 are arranged in generally parallel relation to each other and at an angle of approximately 45° to the longitudinal median line of a shoe in the machine (Fig. 89), the angular disposition of the slides affording toeward and inward movement of the pads. The slides 872 and 878 are mounted in an arm 880 and are urged toward the top margin of the upper by compression springs 882 and 884, respectively mounted in sockets formed in the arm 880 and in similar sockets formed in the backing plates 870 and 876. The arm 880 is mounted for limited angular movement at the upper end of a post 886 which is rectangular in cross-section, the arm being pivoted on a stud 888 projecting upwardly from the post. The angular movement of the arm 880 is limited by a pin 890 projecting upwardly from the upper surface of the arm into a notch in the margin of a disk 892 fixed to the stud 888. The arm is urged in a counterclockwise direction as seen in Fig. 89 by a spring 894 extending from a pin on the arm to a pin on one side of the post. At its lower end the post 886 has a dovetail tongue 896 (Fig. 89) which is mounted for sliding movement in a complementally shaped groove

in a head 898. A spring 900, one end of which is connected to the post 886 and the other end to the head 898, urges the pad assembly away from the shoe and into a position in which the tongue 896 engages the end of a screw 902 (Figs. 90 and 91) mounted in an end plate 904 fixed to the head 898. Extending downwardly from the head is a plate 906 (Fig. 88) which has a tongue and groove mounting in a head 908 at the end of a stem 910, the plate being secured to the head by a clamping nut 912 on the threaded end of a stem 914. The stem 910 is rotatably mounted in the outwardly extending portion of an angular plate 916 (Fig. 51) secured by clamping screws 918 to an arm 920 which carries at its lower end a pin 922 rotatably mounted in bearings in a plate 924 fixed to the upper surface of the rail 790. Pivotally mounted in a yoke 926 (Fig. 88) carried by the arm 920 is a roll 928. When the machine is at rest the roll engages the upper end of a slide 930, as shown in Fig. 51. The angular position of the post 886 relatively to the arm 920 is determined by the angular adjustment of a bent arm 932 fixed to the stem 910. At its lower end the arm 932 is bifurcated as shown in Fig. 88 to embrace a stud 934 projecting outwardly from the arm 920. A compression spring 936 (Fig. 51) surrounds said stud and bears against the bent arm 932. The angular adjustment of said arm is effected by turning a nut 938 mounted on the stud and secured in adjusted position by a lock nut 940. The slide 930 is vertically mounted between four rolls 942 (Fig. 89) on the plate 788. The rolls are mounted respectively on headed screws 944 fixed in the plate 788. Also mounted on said screws are washers 946 which serve as gibs for holding the slide against movement away from the plate. The slide 930 is moved upwardly in predetermined time relation to the operation of the lining wipers by an arm 948 projecting rearwardly from a plate 950 (Fig. 83) fixed to a plate 952 adjustably mounted on the front of the slide 704. As shown in Fig. 83 the arm 948, in the course of its upward movement, engages a roll 954 carried by the slide 930 and extending inwardly therefrom. The slide swings the arm 920 (Fig. 51) into an upright position and the arm is held against return movement by a latch member 956 (Fig. 88) fixed to a shaft 957 which carries at its left end a similar latch member which operates on the top line pad assembly at the left side of the upper. Said latch member is urged in a clockwise direction, as seen in Fig. 88, by a spring pressed plunger 958 mounted in a bore in a barrel shaped extension 960 at the front of the rail 790. The latch member has an angular rear edge face 962 which is engaged by the forward edge face of the arm 920 as it swings upwardly, the latch member swinging in a counterclockwise direction to permit the arm to pass. After the arm has cleared the latch member the plunger 958 swings the latch member in a clockwise direction into its latching position shown in Fig. 88. At the end of the machine cycle the latch member will have been disengaged from the arm 920 and the slide 930 moves downwardly by gravity with the added force of a tension spring 964 (Fig. 1). At an early stage in the second part of the main cycle a power operated plunger 966 (Fig. 106) having an elongated head 968 engages a roll 970 (Figs. 90 and 91) freely mounted in a cylindrical groove in the post 886 and increases the pressure of the top line pads against the top margin of the shoe. During the latter part of the machine cycle the latch member 956 (Fig. 88) is swung in a counterclockwise direction to disengage it from the arm 920 in order to permit the top line pad assembly to swing outwardly away from the shoe. Such counterclockwise movement is imparted to the latch member by the operation of a cam 972 (Fig. 92) fixed to the forward end portion of the horizontal cam shaft 172. The cam acts against a roll 974 carried by a lever 976, as shown in Fig. 92, the lever being pivotally mounted on a fixed fulcrum on the leg 132. The free end of the lever is connected by an ex-

tensible link 980 (Fig. 84) to the rear end of a bent lever 982 pivotally mounted on a screw 984 (Fig. 1) fixed in the plate 788. At its forward end the lever 982 carries a pin 986 (Figs. 88 and 89) which projects inwardly over an arm 988 extending forwardly from the latch member 956. For cooperating with the heel form to cause the shoe upper and the quarter lining to be tensioned toewards and inwardly over an insole on the bottom of the heel form, 10 the illustrated machine is provided with four pairs of gripper jaws constructed and arranged to engage the lasting margins of the upper and the lining, respectively, in the region of the heel breast line. Referring to Fig. 73, gripper jaws 990 and 992 engage the lasting margin of 15 the upper at the left side of the shoe. Gripper jaws 994 and 996 engage the lasting margin of the lining at the left side of the shoe. Gripper jaws 998 and 1000 engage the lasting margin of the lining at the right side of the shoe. Gripper jaws 1002 and 1004 engage the lasting 20 margin of the upper at the right side of the shoe. Referring to Fig. 69, the upper gripping jaw 1002 is formed in a downward extension of a channel member 1006 which has fixed therein a plate 1008 extending upwardly therefrom with a slight inclination to the right. The companion gripper jaw 1004 is formed in the lower portion of a lever 1010 pivotally mounted on a headed screw 1012 projecting rearwardly from the plate 1008. The heightwise position of the upper in the jaws 1002 and 1004 is determined by bringing the edge of the lasting 25 margin into gaging contact with a flat head at the lower end of an arm 1014 mounted in a recess at the left side of the plate 1008 and fixed therein by a set screw 1016 in the channel member. The head of the arm 1014 is positioned adjacent to and in front of the gripper 30 jaws 1002 and 1004. For mounting each upper gripper assembly each plate 1008 has an outward extension 1018 which has secured to its outer end portion a channel member 1020. Referring to Fig. 61, the channel member is pivotally mounted on a screw 1022 in a right angular 35 extension 1024 of a slide 1069. The upper gripper jaws 990 and 992 may be adjusted heightwise of a shoe upper in the machine by swinging movement of the gripper assembly on the screw 1022. The gripper assembly is held in its adjusted position by two abutment screws 40 positioned respectively above and below the pivot screw 1022 and mounted in an ear 1026 projecting rearwardly from the channel member 1020. The upper abutment screw is illustrated in Fig. 61 and identified by the numeral 1028. The abutment screw 1028 and its companion abutment screw bear against a member 1692 carried by the slide 1069. Referring to Figs. 69 and 71, the gripper jaws 1002 and 1004 are closed on the work by the downward movement of a channel member 1042 45 slidably mounted for generally vertical movement on the upper portion of the plate 1008. The sliding movement of said member is directed by a roll 1044 pivotally mounted on a cross pin 1046 extending through the channel member 1042 and positioned in a slot 1048 in the plate 1008. A cam surface 1060 on the channel member 50 1042 engages the upper end portion of the lever 1010 and swings said lever in a clockwise direction, as seen in Fig. 69 during the downward movement of the channel member 1042 by a spring 1052 to close the gripper jaws. To provide for the mounting of the two breast line gripper assemblies at each side of the machine two vertical 55 shafts 1053 (Fig. 1) are mounted in standards 1055 extending upwardly from the table 130 and are supported at their upper ends by brackets 1057 secured to the standards 136. Referring to Fig. 61, there is mounted for angular movement on the shaft 1053 at the left side of the machine a horizontal arm 1059 having an offset hub 1061 which is bored to receive the shaft 1053. The arm 1059 is supported against downward movement on the shaft 1053 by a collar 1063 (Fig. 1) fixed to the shaft 60 1053 by a lock nut 1065. The arm 1059 is held against upward movement on the

shaft by the bracket 1057. Mounted in a guideway extending longitudinally through the arm 1059 are two slides 1065 and 1067, the former providing for the mounting of the upper gripper assembly and the latter for the mounting of the lining gripper assembly. A horizontal arm 1069 extending rearwardly from the upper gripper assembly has a longitudinal tongue-and-groove mounting in the reduced forward portion of the slide 1065 and similarly a horizontal arm 1071 extending rearwardly from the lining gripper assembly has a tongue and groove mounting in the reduced forward portion of the slide 1067. As shown in Fig. 61, the reduction in the slides 1065 and 1067 provides a central longitudinal space between them in which the arms 1069 and 1071 are mounted and the width of the space is such that the two arms are arranged in contiguous relation to each other. To assist in the retention of the arms 1069 and 1071 in the grooves in the slides 1065 and 1067, respectively, suitable retaining members are provided near the forward extremities of the slides and like retaining members are located at points spaced rearwardly on the slides. As shown in Fig. 62, the retaining members each comprises a shoulder screw 1073 extending through a slot 1075 (Fig. 63) formed in the arm. The reduced end portion of the screw extends through a bore in the slide and is secured to the slide by an annular nut 1077. The head of the screw and the nut thereon are mounted respectively in suitable counter bores in the arm and the slide so as not to interfere with the longitudinal movements of the slides and the arms. The slide mounting of the arms in the slides permits independent adjustment of the lining gripper assembly and the upper gripper assembly lengthwise of a shoe upper in the machine. In order to retain each gripper assembly in its adjusted position each arm has pivotally mounted between ears 1079 (Fig. 63) projecting upwardly therefrom a finger lever 1081 having its rear end portion bent downwardly and extended outwardly to provide a detent for engagement in any one of a plurality of spaced notches 1083 formed in the slides. To facilitate the adjustment of the gripper assemblies the notches may be identified with various shoe sizes by suitable identifying marks inscribed beneath them, as shown in Fig. 63. For retaining the detent in the selected notch a spring 1085 is positioned beneath the forward extremity of the finger lever. The normal position of each slide relatively to the arm 1059 is determined by the engagement of a pin 1087 in the slide with the forward extremity of the arm 1059 and this position of the slides is yieldingly maintained by two springs 1089 anchored at their forward ends to the pins 1087 and at their rear ends to pins 1091 mounted in the arm 1059. In order to prevent removal of the slides from the arm two screws 1093 are mounted in the opposite walls of the arms 1059 and have their reduced inner end portions mounted in longitudinal slots formed in the slides, respectively. To provide for movement of the breast line gripper assemblies widthwise of a shoe upper in the machine to and from their respective operating positions the arm 1059 and its companion arm at the right side of the machine are freely mounted on the shaft 1053. As shown in Fig. 59, the arm 1059 is swung toward the upper by a spring 1095 one end of which is anchored to a bracket 1097 secured to the rear end face of the arm 1059 and the other end of which is anchored to a pin 1099 slidably mounted in the vertical portion of an angle bracket 1101 secured to the lower surface of the bracket 1057. The tension of the spring 1095 may be adjusted by turning a wing nut 1103 on the threaded outer end portion of the pin 1099.

The heel end portion of a shoe upper in the machine is tensioned toewards partly by heelward movement of the heel form after the breast line grippers have closed on the shoe upper materials and partly by toewards movement of the breast line gripper assemblies after the heelward movement of the heel form has been completed. For imparting toewards movement to the breast line gripper

assemblies at the left side of the machine a cam 1105 (Fig. 103) is fixed to the cam shaft 178. The cam acts against a roll 1107 mounted on the rear portion of a slide 1109 (Fig. 108) mounted in a horizontal guideway in a plate 1111 secured to arms 1113 fixed to and extending downwardly from a bracket 1115 fixed to the table 130. Pivotally mounted for angular movement between the outwardly projecting ears of a bracket 1117 fixed to the slide 1109 is a barrel 1119 (Fig. 103) in which is slidably mounted a rod 1121 the headed forward end of which is pivotally connected to an arm 1123 fixed to the lower end portion of a vertical shaft 1125. The breast line grippers at the right side of the machine are advanced toewards by a cam 1145 fixed to the shaft 178. The cam 1145 acts against a roll 1147 mounted at the rear end of a slide (not shown) corresponding to the slide 1109 and arranged to act against an arm 1157 fixed to the lower end of a shaft 1151 corresponding to the shaft 1125. The shaft is freely mounted in a bearing formed in bosses 1127 (Fig. 104) projecting respectively upwardly and downwardly from the table 130, the shaft being supported against downward movement by a collar 1129 fixed thereto. At its upper end the shaft 1151 is mounted in a bearing in a bracket 1131 fixed to the standard 136. In each of the assemblies above described the barrel 1119 acts against a spring 1133 surrounding the rod 1121 and confined between the barrel and a collar 1135 fixed to the rod. At its upper end the shaft 1125 has fixed thereto an arm 1137 (Fig. 61), the free end of which is arranged for engagement with the rear end face of a slide 1139 mounted in the rear portion of the arm 1059. The rear portion of the slide 1139 has its inner corner truncated to permit idle movement of the arm 1137 after the slide 1139 has come to the limit of its forward movement. Rearward movement of the slide 1139 is limited by a stop herein illustrated as a screw 1159 mounted in the arm 1059 and projecting into a slot formed in the slide 1139. Concomitantly with the advancement of the breast line grippers the cam 1105 operates to advance the feather line pads at the left side of the upper to bring them into engagement with the back line portion of the upper under relatively light pressure and into engagement with the left side portion of the heel end of the upper under relatively light pressure. Upon the completion of the advancement of the breast line grippers the cam 1137 dwells while the cam 1105 further actuates the feather line pads to cause them to exert sufficient heavy pressure against the left side and heel end of the heel portion of the upper to maintain the tension imparted to the upper by the breast line grippers after the gripper jaws have been opened and retracted to provide clearance for the operation of the breast line wiper and tacker assembly. The slide 1139 operated by the cam 1137 acts on the slide 1065 through a relatively heavy spring 1141 and on the slide 1067 through a relatively light spring 1143. The springs 1141 and 1143 are mounted in suitable open ended grooves in the mutually adjacent end portions of the slides and are confined endwise between the end walls of the grooves and widthwise between the bases of the grooves and the inner walls of the arm 1059. It will be understood that the spring 1141 causes relatively heavy pressure to be imparted to the upper gripper assembly while the spring 1143 causes relatively light pressure to be imparted to the lining gripper assembly.

When the machine is at rest the breast line gripper assemblies are held in their respective retracted positions by two levers 1092 and 1094 (Fig. 59). The cam levers carry at their rear ends, respectively, rolls 1096 and 1098. The roll 1096 bears against a cam 1100 fixed to the cam shaft 176 and the roll 1098 bears against a cam 1102 fixed to the cam shaft 176 and being identical in construction to the cam 1100 but angularly displaced therefrom approximately 60° in a clockwise direction, as shown in Fig. 59. The cam lever 1094 is pivotally

mounted substantially midway between its ends on a fixed fulcrum 1104 and carries in its inturned forward end portion a roll 1106 which bears against an arm 1108 projecting radially to the rear from a collar 1110 located on the lower end of the shaft 1053 (Fig. 1) below the table 130. A roll (not shown) at the forward end of the cam lever 1092 bears against an arm 1112 projecting radially to the rear from the collar corresponding to the collar 1110. Just before the end of the first third of the main cycle of the machine the two cams 1100 and 1102 come into a position in which the cam rolls register respectively with the portions of the cams of smaller diameter thus leaving the breast line gripper assemblies free to be swung inwardly by the action of the spring 1095 and a like spring in the breast line gripper assembly at the right side of the shoe. The gripper assemblies swing inwardly in two steps. The first step brings the gripper assemblies respectively into positions in which the upper gripper jaws are in position to receive the bottom margin of the upper when the heel portion of the upper is in its outspread position, illustrated in Fig. 59. This position of the gripper assembly at the left side of the shoe is determined by the engagement of a pin 1114 (Fig. 67) projecting radially from the hub 1061 with a hook 1116 at the end of a lever 1118 pivotally mounted on an ear 1120 extending upwardly from a collar 1063 fixed to the shaft 1053. During the latter part of the operation of the lining wipers the lever 1118 is swung in a clockwise direction, as seen in Fig. 67, to disengage the hook 1116 from the pin 1114 thus permitting the second step in the inward movement of the breast line gripper assemblies, such movement of the gripper assemblies occurring concomitantly with the closing of the counter from its expanded position, illustrated in Fig. 59, to its normal position indicated in Fig. 58. As shown in Fig. 67, the link 816 acts on the inner end portion of the lever 1118 which is bifurcated to straddle the link and is positioned above and in contiguous relation to a collar 1122 fixed to the link. The second step in the inward movement of the breast line grippers is controlled by the operator who, at this stage in the operation of the machine, has taken hold of the opposite marginal portions of the upper in the machine at points just forwardly of the heel breast line and has inserted the lasting margin at opposite sides of the upper between the upper gripping jaws. The operator maintains the position of the lasting margin between the gripper jaws as the jaws swing inwardly into their operating position illustrated in Fig. 61 and thus determines the position of the gripper assemblies widthwise of the upper when the jaws close. In the event that the machine is operated without a shoe upper therein the second step in the inward movement of the breast line gripper assemblies is terminated by the engagement of a bent pin 1124 (Fig. 68) mounted in the hub 1061 of the arm 1059 with a pin 1126 mounted in the collar 1063 and by the mutual engagement of similar pins in the assembly at the right side of the machine.

Referring to Fig. 65, illustrating the lining gripper jaws, the jaw 998 is formed in the low end portion of an arm 1138 which extends downwardly and to the left from the lower portion of the plate 1140 and, as shown in Fig. 66, is bent to cause the gripper jaw 998 to be offset heelwardly from the plate 1140 thereby to bring the jaw into alignment with the upper gripping jaws widthwise of a shoe in the machine. Similarly the gripper jaw 1000 is formed in the lower end portion of an arm 1142 extending from a plate 1144, said arm being constructed and arranged to locate the jaw 1000 in registration with the jaw 998. The plate 1144 has an upwardly extending arm 1146 the upper end portion of which is pivotally mounted on a screw 1148 projecting forwardly from the plate 1144. In order to hold the lining gripper jaws in registration with each other the plates 1140 and 1144 are held in contact with each other by a headed screw 1150 mounted in the plate 1144 and extending through a slot 1152 formed in

the plate 1140. For closing the lining gripper jaws a cam plate 1154 is arranged in contiguous relation to the front face of the plate 1144 and is slotted to receive two guide rolls 1156 (Fig. 66). The cam plate is held against the plate 1144 by a retaining plate 1158 secured in spaced relation to the plate 1144 by shouldered bolts 1160 which also serve as a mounting for the rolls 1156. A spring 1162 (Fig. 65) urges the cam plate downwardly causing it to act on an arm 1164 extending upwardly from the plate 1140 thereby moving said plate to the right, as seen in Fig. 65, to close the gripper jaws. For mounting the lining gripper assembly the plate 1144 is extended to the right, as seen in Fig. 65, and is provided at its end portion with an angular extension 1166 (Fig. 59) which provides the forward wall of a notch in which is received an ear 1168 projecting laterally from a forward extension 1170 of the arm 1071. The plate 1144 is pivotally mounted on a screw extending through the extension 1166 and the adjacent end portion of the plate 1144 and also through the ear 1168. The plate 1144 is adjusted angularly about a screw 1172 and is secured in adjusted position by abutment screws 1174 (Fig. 65) mounted in an ear 1176 projecting from the extension 1166, said screws bearing against the extension 1170. When the machine is at rest the upper gripping jaws are held in their open position, as shown in Fig. 69, by a latch member 1178 pivotally mounted on a headed screw 1180 extending forwardly from the plate 1018, the latch member being arranged to engage a shoulder formed in the channel member 1042. The latch member is operated by a spring 1182 connected to its downwardly extending tail portion 1184. In order that the latch member may serve to hold the lining gripper jaws 998 and 1000 in their open position, as shown in Fig. 65, the cam plate 1154 has fixed in its upper end portion a pin 1186 arranged to extend rearwardly from the cam plate for engagement with the upper surface of an ear 1188 extending rearwardly and to the right from the upper end of the channel member 1042 (Fig. 69). The latch member 1178 is released by the operation of the lining wiper treadle to permit the lining gripper jaws and the upper gripper jaws to close simultaneously upon the work. As heretofore described, the operation of the lining wiper treadle imparts downward movement to the free end of the lever 862 (Fig. 69). The lever 862 is mounted to swing on a fulcrum 1190 in the extension 1020. The upwardly extending inner end portion of the lever 862 is connected by a link 1192 to the latch member 1178 and the operation of the lever by the lining wiper treadle disengages the latch member from the shoulder in the channel member 1042 to permit the gripper jaws to close on the work.

For opening the breast line gripper jaws just prior to the operation of the wiper and tacker units a cam 1194 (Fig. 10) is fixed to the shaft 176 and arranged to operate against a roll 1196 pivotally mounted at the free end of an arm 1198 fixed to a rock shaft 1200. The rock shaft has fixed to its opposite end portions two arms, one of which is illustrated in Fig. 10, and identified by the numeral 1202. The two arms are connected by links 1204 (Figs. 10 and 60) to lugs 1206 projecting rearwardly from a slide 1208 mounted for vertical movement in suitable ways in the standard 312. At its upper end the slide has a horizontal portion 1210 which extends forwardly and laterally from the slide. At its left end the horizontal upper portion 1210 of the slide has a ball-and-socket connection to the lower end of a link 1212 the upper end of which has a ball-and-socket connection to the rear end of a lever 1214 (Fig. 59) of irregular shape mounted to swing on a fulcrum 1216 in the arm 1059. The operation of the cam 1194 imparts upward movement to the forward end of the lever 1214 which, as shown in Fig. 59, engages the bottom surface of the ear 1188 at the upper end of the channel member 1042. The upward movement of the channel member opens the upper gripper jaws 1002 and 1004 and at the extremity of the upward move-

ment of the channel member the spring 1182 (Fig. 69) operates the latch member 1178 to hold the channel member 1042 against downward movement. During its upward movement the ear 1188 bears against the pin 1186 (Fig. 66) in the cam plate 1154 moving the cam plate upwardly to open the lining gripper jaws.

The breast line gripper assemblies at opposite sides of the shoe upper are similar in construction and operation and it will be understood that the foregoing description, wherever it refers to the organization of only one of said assemblies, is equally applicable to the other.

The illustrated machine is provided with means for mounting alternatively a plurality of metal heel forms of different sizes. Each heel form serves a run of three full shoe sizes and is readily removable from its mounting means for replacement by a heel form of a different size. Referring to Fig. 106, illustrating a heel form 166 in the heel end portion of a shoe upper in the machine, the illustrated heel form is bilaterally symmetrical and has a convex insole supporting surface which serves to clench the lasting tacks whereby the bottom margins of the shoe upper material are secured to the insole 526. The heel form is supported against downward movement by a member 1222 mounted at the upper extremity of the lining wiper carrier and is positioned vertically by two abutment screws 524 on the counter carrier which operate in conjunction with the counter gripping means to provide a three point bearing which determines both the vertical position of the heel form and the angular disposition thereof. At the area of contact of the form supporting member 1222 the illustrated heel form is provided with a plane surface corresponding to the plane cone face of a shoe last. Referring to Fig. 100, the rear portion of the heel form is slabbed off at 1226 to provide clearance for the gripper jaw 208. For positioning and orienting the insole 526 on the bottom of the heel form the form carries two positioning pins 1228 which, as shown in Fig. 100, project upwardly from the heel form through suitable apertures in the heel end portion of the insole. The pins 1228 are arranged in upwardly converging relation to each other to enable them to hold the insole against displacement from the bottom of the heel form during the movement of the heel form into the supported upper. Each pin 1228 projects upwardly from the upper end of a rod 1230 through suitable bores in the heel form. The rod 1230 is slidably mounted in a counter bore 1232 for sliding movement to move the pin to and from insole retaining position. The rods are operated simultaneously to move the pins to and from insole retaining position by a manually operated sliding plate 1234 positioned in a horizontal bore in the lower portion of the heel form and located between the downwardly extending legs of the bifurcated lower end portions of the rods 1230. At its forward end the plate 1234 has a cylindrical head 1236 provided with a knurled knob 1238 conveniently arranged for engagement by the operator. Plate 1234 is provided with two parallel cam slots 1240 extending rearwardly with a downward inclination and arranged to receive, respectively, cross pins 1242 mounted in the bifurcated lower end portions of the rods. It will be seen that forward movement of the sliding plate 1234, from its position illustrated in Fig. 100, retracts the pins 1228 from the insole and rearward movement of the slide moves the pins upwardly into insole engaging position. The slide 1234 is retained in either of two predetermined positions lengthwise of the form 166 by a spring ball latch 1244 mounted in the heel form and arranged to engage either of two recesses 1246 formed in the slide. For mounting the heel form 166 on an arm 1248 the heel form has a stem 1250 projecting forwardly from its plane forward surface through a bore in a head 1252 at the free end of the arm. The stem 1250 is slightly longer than the bore in the head and the

portion of the stem projecting beyond the head has mounted in a diametrical bore therein a double ball latch 1254 which engages the forward end face of the hub to retain the form on the head 1252 while permitting it to be readily removed therefrom. Referring to Fig. 74, the head 1252 has a flange 1256 in its rear portion, said flange having a notch 1258 through which projects a pin 1260 in the heel form 166 thus providing for a limited swiveling movement of the heel form in the head. The swivel mounting of the heel form on the arm 1248 permits the heel form sufficient angular adjustment to permit the abutment screws 524 to determine the angular disposition of the heel form relatively to a shoe upper in the machine. The arm 1248 is pivotally mounted on a headed screw 1262 at the free end of a short arm 1264 fixed to a horizontal shaft 1266 extending from front to back of the machine and journaled at its rear end for rotary and endwise movements in a bearing in a fixed block 1268 (Fig. 79) and at its forward end in a bearing 20 in a head 1270 at the upper extremity of a flat angle plate 1272 secured to the standard 1072. The arm 1248 is normally held in its position relatively to the short arm 1264 illustrated in Fig. 74 by a compression spring 1274 positioned between an upwardly extending end portion 1276 of the short arm 1264 and an upstanding end portion 1278 of the arm 1248. The normal position of the two arms is determined by the engagement of an offset portion 1280 of the arm 1248 with a similar offset portion 1282 of the short arm 1264. The illustrated construction of the compound carrier comprising the arms 1248 and 1264 permits the heel form 166 to come to rest in the heel portion of the upper against abutment members hereinbefore described before the shaft 1266 has fully completed its rotary movement, the short arm 1264 moving angularly relatively to the arm 1248 during the latter part of the rotation of the shaft after the movement of the heel form 166 has been arrested by the abutment members. During the return movement of the heel form the spring 1274 returns the arms 1248 and 1264 to their normal position relatively to each other, illustrated in Fig. 74. The shaft 1266 is actuated by a constantly driven shaft 198 (Fig. 79) upon the operation of a clutch mechanism hereinafter described by the hand lever 202. For imparting rotary movement to the shaft 1266 a cam 1284 (Fig. 82) is fixed to the shaft 198. The cam 1284 has a path or groove 1286 in which operates a roll 1288 pivotally mounted at the lower end of a rack 1290 slidably mounted in a guideway in a bracket 1292 fixed to an upright 1294 mounted on the table 130 and being one element of a superstructure on the rear portion of the table. The rack 1290 meshes with a pinion 1296 fixed to the shaft 1266. The pinion is elongated, as shown in Fig. 79, so that it will maintain meshing engagement with the rack 1290 during the endwise movement of the shaft 1266. For imparting such endwise movement to the shaft a cam 1298 is fixed to the shaft 198 (Fig. 81). The cam has formed therein a path or groove 1300 in which operates a roll 1302 pivotally mounted at the lower end of a slide 1304 mounted in a suitable guideway in the bracket 1292. Pivotally mounted at the upper end of the slide is a link 1306 having a stem 1308 (Fig. 79) projecting from its upper end. Slidably mounted on the stem is a block 1310 which is pivotally connected to an arm 1312 fixed to a shaft 1314 journaled in bearings in horizontal rails 1316 forming the upper portion of the superstructure. Also fixed to the shaft 1314 is an arm 1318 extending downwardly therefrom and having its bifurcated lower end portion notched to engage pins 1320 projecting in opposite directions from a block 1322 fixed to the shaft 1266. In order to provide a variable rearward movement of the shaft 1266 a spring 1324 is mounted on the stem 1308 and confined between the block 1310 and a nut 1326 on the threaded end portion of the stem. The

rearward movement of the shaft 1266 is arrested when the heel form comes to the limit of its rearward movement and continued operation of the cam 1298 thereafter causes the stem 1308 to slide downwardly through the block 1310 compressing the spring 1324. During the operative movement of the heel block 166 the shaft 1266 is rotated approximately 90° in a clockwise direction, as seen in Fig. 74, to advance the heel form from its full line position in said figure to its position illustrated in broken lines. Upon the completion of its rotary movement the shaft is moved endwise rearwardly to advance the heel form into the heel end portion of a shoe upper in the machine. During its rearward movement the heel form is maintained in its relation to the upper heightwise thereof, shown in Fig. 100. In this position the insole mounted on the form is spaced vertically from the margin of the lining sufficiently to insure the advancement of the heel form together with the insole into its position shown in Fig. 100 without contact of the insole with the margin of the lining. As the heel form and the insole thereon move rearwardly from their position in Fig. 100 to their position illustrated in Fig. 101 the shaft 1266 is rotated slightly in a reverse direction to move the heel form upwardly into its position illustrated in Fig. 101 in which the margin of the insole is pressed firmly against the margin of the lining. The rearward extremity of the heel form is in contact with the back line portion of the lining during the rearward movement of the lining with the form from its position in Fig. 100 to its position illustrated in Fig. 101 and consequently the upper is urged heelwardly against the pressure of the springs 1141 and 1143 (Fig. 61) which resist heelward movement of the breast line gripper jaws which at this time are closed on the upper and the lining. Thus, lengthwise tension is imparted to the heel end portions of the upper and the lining along lines extending from the breast line gripper to the central portion of the back line during the final increment of rearward movement of the heel form and the tension thus effected is maintained by the breast line grippers until feather line pads hereinafter described grip the heel end portion of the upper against the form to maintain the tension imparted to the upper and the lining after the breast line grippers are opened and retracted and until the upper is wiped inwardly and secured by cement or by suitable fastenings, herein illustrated as lasting tacks, to the insole. It will be understood that the degree of tension imparted to the upper and the lining may be varied as required by adjusting the position of the abutment member 272 with relation to the back line portion of the upper. During the operation of the heel form the forepart of the upper is turned downwardly into the position shown in Fig. 79 to provide clearance for the advancement of the heel form. In order to obviate undue distortion of the upper by the engagement of the arm 1248 with the lasting margin of the upper during the heelward movement of the heel form that portion of the arm which engages the upper is forwardly offset at 1328, as shown in Fig. 93. The advancement of the heel form is initiated by the operation of the hand lever 202 (Fig. 79) which causes the clutch on the cam shaft 198 to connect the shaft to the constantly rotating gear 196. The hand lever 202 (Fig. 74) swings on a fixed fulcrum 1330 and the rear portion of the hand lever is connected by a link 1332 to an arm 1334 fixed to a rockshaft 1336 extending from front to rear of the machine and journaled in bearing members 1338 (Fig. 79) fixed to the table 130. Fixed to the rear portion of the rockshaft is an arm 1340 which actuates a clutch mechanism indicated generally by the numeral 1342 to connect the cam shaft 198 to the constantly driven gear 196. The cam 284 on the shaft 198 causes the cam shaft to be disconnected from the gear 196 at the end of 180° of rotation of the cam shaft thus causing the heel form to come to

rest at the end of its heelward movement. During the latter part of the machine cycle, after the wiping and tacking operations have been completed and the wipers have been retracted, the clutch 1342 is automatically operated by a cam 1344 (Fig. 75) to cause the heel form to be returned to its rest position, illustrated in full lines in Fig. 74. The shoe upper moves with the heel form during its retracting movement and the assembly comprising the insole 526 and the shoe upper, which is now secured to the heel end portion of the insole, is released from the heel form by the retraction of the pins 1228 to permit the assembly to be removed therefrom. As shown in Fig. 75, the cam 1344 operates on a roll 1358 at the free end of a lever 1360 having a fixed fulcrum 1362 on the leg 132 and connected by a link 1364 to an arm 1366 fixed to the forward end of the shaft 1336. In order to prevent inadvertent operation of the hand lever 202 at an improper time, a detent 1346 (Fig. 74) is constructed and arranged to hold the hand lever in its rest position. Just prior to the first interruption in the main cycle of the machine the detent is retracted by the operation of a cam 1348 (Fig. 75) on the shaft 172 to permit the operation of the hand lever. The cam 1348 acts against a roll 1350 at the free end of an arm 1352 pivotally mounted at 1354 on the leg 132, the arm being connected by a link 1356 to the detent 1346. During the wiping and tack driving operations the heel form is positively held against downward movement by a generally wedge shaped member 1368 (Fig. 87), hereinafter referred to as a wedge, slidably mounted for horizontal movement in grooves 1370 (Figs. 85 and 87) formed in the arms 708 and in arms 1372 secured to the arms 708 and extending rearwardly therefrom. The wedge takes the downward force applied by a foot 1374 carried by the slide 718. The foot is connected to the lower end portion of the slide by a turn buckle 1376 which engages a right-hand threaded stem 1378 projecting upwardly from the foot and a left-hand threaded rod 1380 which is pivotally mounted at its upper end on a crosspin 1382 fixed in the bifurcated lower end portion of the slide. The foot 1374 is confined to movement in a vertical path by a roll 1384 pivotally mounted on a screw in the right side of the foot and mounted in a slot 1472 in the right arm 708 (Fig. 1). The wedge 1368 is moved to the left as seen in Fig. 87 by means hereinafter described to bring its stepped upper surface 1386 into engagement with the complementally stepped lower surface 1388 of the foot 1374 after the slide 718 has been moved upwardly into form supporting position. Thus, it will be seen that the form supporting slide is held against downward movement by mutually engaging horizontal surfaces formed in the slide and in the foot and consequently the downward pressure of the foot against the wedge will not exert against the wedge any horizontal component of movement tending to dislodge the wedge from its supporting position. The wedge 1368 is moved forwardly into its position beneath the foot 1374 by the expansion of a spring 1390 (Fig. 85) which is energized by the operation of a cam 1392, the initial advancement of the wedge being timed by the withdrawal of a pin 1394 (Fig. 87) constructed and arranged to engage the recessed forward surface 1396 of the wedge. The spring 1390 surrounds a rod 1398 the forward end of which extends through an opening in a lug 1400 (Fig. 87) projecting downwardly from the wedge 1368, and the other end of which is provided with a head 1402 (Fig. 85) having a reduced extension which is pivotally mounted between ears 1404 projecting upwardly from a horizontal carrier or bar 1406 mounted for movement forwardly and rearwardly of the machine on two rollers 1408 (Fig. 1) pivotally mounted between fixed ears 1410. Referring to Fig. 86, each roller is provided with two flanges 1414 which engage opposite sides of the bar 1406. In order to compress

the spring 1390 the cam 1392 imparts forward movement to the bar 1406 through mechanism now to be described. Referring to Fig. 85, two parallel levers 1416 are mounted to swing on a fixed fulcrum 1418 and carry between them a cam roll 1420 arranged to be engaged by the cam 1392. A spring 1422 acting on the levers 1416 holds the wedge in its retracted position illustrated in Fig. 85. Pivotally mounted between the free ends of the parallel levers 1416 is a link 1424 the forward end of which is pivotally mounted between parallel levers 1426 mounted to swing on a fixed fulcrum 1428. Pivotally mounted between the free ends of the parallel levers 1426 is a link 1430 the forward end of which is connected to the bar 1406 by mechanism illustrated in Fig. 86 comprising a plate 1432 which is bent to straddle the rod 1398 and the spring 1390 and has its ends secured to the upper portion of the bar. Projecting upwardly from the top of the bent plate 1432 is a stud 1434 on which is pivotally mounted the free end of the link 1430. In order to prevent the wedge 1368 from striking the foot 1374 with undue velocity a dashpot mechanism is provided as shown in Fig. 85, said mechanism comprising a piston 1436 mounted in a cylinder 1438, said piston being connected at its rear end to a bent arm 1440 fixed to the rear end face of the wedge 1368. The cylinder is secured by split clamps 1442 to the left arm 708. The pin 1394 (Fig. 83) is slidably mounted for horizontal movement widthwise of the machine in a hole in the left arm 1372. For withdrawing the pin 1394 to permit the spring 1390 to advance the wedge into heel form supporting position a bell crank lever 1444 (Fig. 83) is pivotally mounted in the bifurcated left-hand portion of a pin 1446 fixed to the left arm 1372. The discoidal end portion of the vertical arm of the lever 1444 is positioned in a notch formed in the pin 1394. The end of the horizontal arm of the bell crank lever is connected to a link 1448 having a universal connection to a rocker lever 1450 (Fig. 1) pivotally mounted on the left arm 708, the forward end portion of said lever being connected by a link 1452 to a bent lever 1454 (Fig. 79) mounted to swing on a shaft 1456. The free end portion of the lever 1454 is positioned in the path of rearward movement of the arm 1248 of the heel form assembly. Thus, it will be seen that the lever 1454 is actuated during the rearward movement of the heel form into the supported upper to retract the pin 1394 in order to permit the advancement of the wedge by the spring 1390. Inasmuch as the slide 718 is at the limit of its downward movement when the heel form is advanced into the upper the wedge 1368 is advanced in two steps, the first occurring when the slide is in its position illustrated in Fig. 87, and the second step occurring after the slide has been elevated into heel form supporting position.

In order to prevent undue wear of the stepped surfaces of the wedge 1368 and the foot 1374 the illustrated machine is provided with pawls 1458 and 1460 (Figs. 1 and 83) for holding the heel form supporting assembly against downward movement during the retraction of the wedge. The pawls are pivotally mounted on a pin 1462 mounted in a bracket 1464 fixed to the right arm 708. The pawl 1458 has a forwardly extending tail portion which is pivotally connected to the lower end of a link 1466 which moves downwardly by its own weight to operate the pawl and is moved upwardly by mechanism hereinafter described to retract the pawl. The pawls operate against ratchet teeth in a plate 1468 fixed to the last supporting slide. The pawl 1460 is not connected to the link 1466 but is retracted by the engagement of a pin (not shown) projecting laterally from the pawl 1458 with a stem 1470 projecting forwardly from the pawl 1460. During the latter part of the machine cycle the link 1466 is moved upwardly to disengage the pawls from the ratchet teeth thereby to permit

the last supporting assembly to move downwardly into its rest position which is determined by the engagement of the roll 1384 at the base of the vertical slot 1472 in the arm 708. The upward movement of the link

- 5 1466 is effected by the operation of the cam 972 (Fig. 92) which imparts upward movement to the link 980 and counterclockwise movement to the lever 982 (Fig. 1). Said lever has a downward extension 1474 which carries at its extremity a roll arranged to engage a rocker 10 lever 1476 pivotally mounted on the plate 788. At its forward end the rocker lever carries a pin which extends laterally into a position beneath an arm 1478 fixed to the shaft 1456 mounted to rotate in bearings in a fixed plate 1482. Also fixed to the shaft 1456 is an arm 1484 on which is pivoted the link 1466 which carries at its extremity a roll arranged to engage a rocker 15 956 on the left side.

Referring to Fig. 97, illustrating the organization of 20 the feather line pad assembly, the pads 1486 and 1488 are constructed and arranged to engage the outer surface of the upper beginning at points adjacent to the back line and extending toward about the heel end portion of the upper.

25 The feather line pads 1490 and 1492 engage the upper beginning at points adjacent to the toeward ends of the pads 1486 and 1488 and extending toward therefrom to the breast line region of the upper. The construction and operation of the feather line pads at opposite sides of the upper being identical, only the

30 assembly at the left side of the machine will be described in detail, and it will be understood that this description is equally applicable to the mechanism at the opposite side. Referring to Fig. 93, the illustrated pads comprise two layers of leather mounted on rigid plates or shoes

35 1494 and 1496, respectively. The shoe 1494 is provided with lugs 1498 between which the forward end portion of a slide 1500 is pivotally mounted. Similarly the shoe 1496 is provided with lugs 1502 for pivotally mounting a slide 1504. The two slides are mounted in forwardly

40 converging ways in a head 1506 having a downwardly extending hub 1508 (Figs. 94 and 95) which is freely mounted on a shaft 1510 (Fig. 105) fixed in a vertically disposed cylindrical head 1512 at the forward end of a slide 1514 which moves to the right, as seen in Fig. 94, to bring the pads into shoe engaging position. The slide is mounted in a guideway in a member 1516 (Fig. 93) having a hub 1518 (Fig. 95) which is freely mounted for angular movement on the post 1053 and is arranged

45 at an angle of approximately 45° to the longitudinal median line of a shoe upper in the machine by engagement with an abutment screw 1520 (Fig. 95) mounted in an upwardly extending ear 1522 at the end of a lateral extension 1524 of a collar 1526 fixed to the post 1053 and arranged to support the member 1516. The

50 head 1506 (Fig. 93) is normally oriented by the engagement of a pin 1528 projecting upwardly therefrom with the wall at the rear end of a notch 1530 formed in a disk 1532 clamped to the upper end of the shaft 1510 by a headed screw 1534. Each of the pads 1488 and

55 1492 is acted on by two compression springs 1536 mounted in sockets in the head 1506 and seated in sockets formed in the shoes 1494 and 1496, respectively. When the machine is at rest with the pads in their positions shown in Fig. 93 the springs 1536 urge the pads forwardly into their positions shown in said figure, in which positions cross pins 1538 in the rear portions of the slides 1500 and 1504, respectively, engage the rear face of

60 the head 1506. Referring to Fig. 104, the two pads at the right side of the machine are advanced into shoe engaging position by the operation of the cam 1154, this being the same cam which imparts toeward movement to the breast line grippers at the right side of the machine. The cam 1154 imparts angular movement to the shaft 1151 through connections hereinbefore de-

scribed. At its central portion the shaft 1125 has fixed thereto an arm 1540 (Fig. 93) which is connected by a link 1542 to two identical L-shaped members 1544 pivotally mounted at their elbows on a headed pin 1546 carried by a lug 1548 projecting outwardly from the slide 1514. In the operation of the machine the L-shaped members swing in a clockwise direction, as seen in Fig. 93, bringing front surfaces into engagement with an angular member 1550 (Fig. 99) slidably mounted on the slide 1514. The member 1550 is held against forward movement on the slide by a pawl 1552 (Fig. 93) which engages any one of a plurality of ratchet teeth formed in the member 1550. Thus it will be seen that the cam operated arm 1540, after a measured lost motion, advances the slide 1514 which mounts the feather line pads at the right side of the machine. To provide for the mounting of the angular member 1550 the slide 1514 has formed therein a slot 1554 (Figs. 94 and 99), and in said slot is mounted a tongue 1556 formed in said angular member 1550. The angular member is held against movement away from the slide 1514 by a keeper plate 1558 (Fig. 99) secured to the tongue and mounted in a clearance groove 1560 formed in the member 1556. The pawl 1552 is urged in a counterclockwise direction, as shown in Fig. 93, into engagement with one of the ratchet teeth in the member 1550 by a torsion spring 1562 mounted on a pin projecting upwardly from the pawl 1552. The rear end of the spring has formed therein an eye 1564 which permits the spring to be slidably mounted on a pin 1566 carried by the member 1550, the forward end of the spring bearing against a pin 1568 projecting upwardly from the pawl. The orientation of the head 1506 relatively to a shoe in the machine is determined by the engagement of the rear end wall of the notch 1530 in the disk 1532 (Fig. 93) with the pin 1528 projecting upwardly from said head, this relation of the pin and the disk being yieldingly maintained by a flat spring 1570 (Fig. 98) mounted in a bracket 1572 secured to the head 1512 by a clamping screw 1574 extending through an open ended slot in the arcuate portion 1576 of the bracket. The free end of the spring is positioned between two pins 1578 extending downwardly from the forward portion of the head 1506. The spring pressed plunger 966, which actuates the top line pads, is mounted in a counter bore in an arm 1580 fixed to and offset laterally from the head 1512. For retracting the feather line pads there are fixed to the shaft 178 (Figs. 104 and 107) two arms 1582 each carrying at its free end a roll 1584. During the latter part of the machine cycle each roll engages the rear surface of a plate 1586 fixed to a flat angle bracket 1588 secured to a slide 1590 mounted in a horizontal guideway in a plate 1592 (Fig. 108) fixed to the stationary arm 1113. Referring to Fig. 103, the slides 1590 are connected to arms 1594 fixed to the shafts 1125 and 1151 by links 1596 the forward ends of which are pivotally mounted on bolts 1598 in the slotted ends of the arms 1594 and the rear portions of which carry blocks 1600 which are pivotally mounted on lugs 1602 projecting outwardly from the slides 1590. The operation of the left arm 1582 rotates the shaft 1125 in a clockwise direction, as seen in Fig. 93, thereby retracting the feather line pads into their position shown in Fig. 93. When the machine comes to rest, the arm 1582 is in its position shown in Fig. 104. At an early stage in the power cycle of the machine the roll 1584 (Fig. 103) moves out of engagement with the plate 1586 leaving the slide 1590 (Fig. 107) free to be advanced by the cam 1145, as hereinbefore described. The slide 1514 (Fig. 93) is advanced in two steps by the operation of the cam 1145. In the first step the plunger 966 (Fig. 98) operates to apply heavy pressure to the top line pads while the feather line pads 1486 and 1490 apply relatively light pressure to the upper. While the pressure of the feather line pads against the upper remains rela-

tively light, the breast line grippers are advanced toewards as hereinbefore described to tension the upper about the heel form 166. In the second step of the operation of the cam 1145 relatively heavy pressure is applied to the feather line pads, the breast line grippers at this time having completed their toeward movement and come to rest. The heavy pressure of the feather line pads against the upper maintains the toeward tension imparted to the upper by the breast line grippers after the grippers have been opened and retracted and thereafter during the breast line wiping and tacking operations.

For wiping the lasting margin at the back line portion of a shoe upper in the machine in over an insole mounted on the heel form, the illustrated machine is provided with two identical wipers one of which is illustrated in Figs. 109 to 115. Referring to Fig. 112, the illustrated wiper member is a cylindrical head 1604 at the lower end of a rod 1606 slidably mounted in a sleeve 1608 which is mounted for angular movement from its position illustrated in Fig. 112 to its position in Fig. 113. To facilitate the overwiping movement of the wiper head its lower extremity has formed therein a beveled surface 1610 and the wiper head is rounded slightly at the junction of the bevel and the cylindrical surface of the head. For mounting the sleeve 1608 for angular movement in a vertical plane generally parallel to the longitudinal median line of the heel form two brackets 1612 (Figs. 60 and 109) are fixed to the horizontal arm 264 at the upper extremity of the standard 248. As shown in Fig. 60 the sleeve 1608 and a like sleeve 1614 which mounts the right-hand wiper assembly are positioned between the two brackets with their inner hubs 1616 in contiguous relation to each other and their outer hubs 1618 in contiguous relation to the brackets. The inner hubs 1616 are drilled to receive a pin 1620 (Fig. 109) which is coextensive with the hubs and the hubs are keyed to the pin in order to hold the two sleeves against relative angular movement. Fixed in the outer hubs 1618 and extending through bearings in the brackets 1612 are two pins 1622 which have fixed to their outer end portions projecting beyond the brackets two arms 1624 which are actuated to impart overwiping movements to the wipers. As shown in Fig. 113, the brackets 1612 have their upper portions extended forwardly to locate the bearings for the sleeves 1608 and 1614 in positions such that the wiper assemblies are located in vertical positions over the lasting margins of the upper when the wipers have completed their overwiping movements. This disposition of the wiper assemblies provides the most desirable arrangement of the tack driving instrumentalities relatively to the insole 526 during the tack driving operation. In the illustrated organization a tack such, for example, as the tack 1626 illustrated in Fig. 113, is fed from any suitable source through an angular bore 1628 extending through a rearward extension 1630 of the head 1604 and communicating with an axial bore 1632 extending through the head 1604 and the lower portion of the rod 1606. For driving the tack 1626 a pin 1634 is slidably mounted in the bore 1632, said pin having at its upper extremity a head 1636 slidably mounted in a counterbore 1638 extending from the bore 1632 upwardly to the upper extremity of the rod 1606. The tack driving pin 1634 is actuated by a spring 1640 mounted in the counterbore 1638 and confined between the head 1636 and a disk 1642 at the lower extremity of an abutment screw 1644 adjustably mounted in a cap 1646 mounted on the threaded upper extremity of the rod 1606. When the machine is at rest the wiper head is in its position illustrated in Fig. 109. In this position the wiper head is held at the limit of its downward movement relatively to the sleeve 1608 by a spring 1648 surrounding the lower portion of the rod 1606 and confined between the lower extremity of the sleeve 75 1608 and the shoulder 1650 defining the upper extremity

of the head 1604. During the first stage of the overwiping movement the spring 1648 yields as the wiper head moves upwardly relatively to the sleeve 1608 and the spring maintains suitable wiping pressure of the wiper head against the lasting margin of the upper. The tack driving spring 1640 is loaded for the tack driving operation during the overwiping movement of the wiper head by mechanism now to be described. In order to maintain the desired relation between the wiper head and the lasting margin of the upper at this time and also to provide means for holding the wiper assembly against upward movement during the final loading of the tack driving spring, two pins 1652 are mounted in the lower portion of the rod 1606 and arranged to be seated in notches 1654 (Fig. 114) in the lower extremity of the sleeve 1608. For loading the spring 1640 during the advancement of the wiper assembly a lever 1656 (Fig. 109) is mounted to turn on a pin 1658 projecting from the bracket 1612. Referring to Fig. 3, two arms projecting forwardly from the hub of the lever carry latch members 1660 arranged in contiguous relation to the sleeve 1608 at opposite sides thereof. During the advancement of the wiper assembly the lever 1656 swings in a clockwise direction, as seen in Fig. 109, and the two latches 1660 engage the slotted off end portions of a cross pin 1662 mounted in the head 1636 of the driving pin 1634 and extending through longitudinal slots 1664 (Fig. 112) in the counterbored portion of the rod 1606 and similar longitudinal slots 1666 (Fig. 109) formed in the sleeve 1608. The rear end portions of the arm 1624 and the lever 1656 are mounted on a cross pin 1668 in a yoke 1670 fixed to the upper end of a link 1672, the end portion of the lever 1656 being slotted to provide for the differential movement of the lever and the arm 1624. Referring to Fig. 10, the wipers and the tack drivers are actuated by the cam 1194 which also operates the mechanism for opening the breast line gripper jaws and the back line gripper jaws. Referring to Fig. 34, the cam 1194 imparts downward movement to the slide 1208 to which the lower end of the link 1672 is pivotally connected. During the downward movement of the slide 1208 the arm 1624 swings the wiper assembly from its position in Fig. 109 to its position illustrated in Fig. 113 and, concomitantly, the lever 1656 is swung in a clockwise direction from its position in Fig. 109 to its position in Fig. 113, loading the spring 1640 for the tack driving operation. During the advancement of the wiper assembly the cross pin 1662 moves forwardly relatively to the latch members 1660 until it clears the latch members in its position shown in Fig. 113 and the spring 1640 actuates the pin 1634 to drive the tack 1626. The tack is driven through the lasting margin of the upper, the flange of the counter 364, the margin of the lining and the margin of the insole 526 and is clenched against the upper surface of the metal heel form. During the return movement of the lever 1656 to its position in Fig. 109 the latch members 1660 engage the upper surface of the cross pin 1662 and swing in a clockwise direction until they clear the cross pin whereupon leaf springs 1674 return the latch members to their normal positions.

In the manufacture of shoes in which the upper materials at the heel end are secured to the insole and to each other by cement and no heel end lasting tacks are driven, the wiper head 1604 is provided with a cap 1676 (Figs. 110 and 111), the cap being held in position on the wiper head by two springs 1678 anchored at their lower ends to pins at opposite sides of the cap and at their upper ends to pins at opposite sides of the wiper head. In order to insure an effective cement bond between the upper materials and the insole the tack driving pin is operated at the end of the wiping stroke to impart a hammer blow to the cap 1676 and through the cap, which, it will be remembered, is yieldingly mounted, to the overlasted margin of the upper.

The construction of the wiper and tacker units at the opposite sides of the breast line portion of the upper is substantially the same as the construction of the back line wiper and tacker units above described. However, the connections whereby the breast line wiper and tacker units are operated differ from the connections for the back line units by reason of the fact that the breast line wiper and tacker units are required to move with the breast line gripper jaws widthwise of a shoe upper in the machine into operating position and lengthwise of the upper during the upper tensioning operation. To this end the breast line wiper and tacker unit 1680 (Fig. 61) at the left side of the shoe is mounted in a housing 1682. The main support for the housing comprises a shaft 1684 for actuating the wiper and a shaft 1686 for loading the tack driving spring. At their forward ends these shafts are mounted in bearings in the housing and their rear portions are slidably mounted in sleeves 1688 and 1690, respectively. In order to hold the housing 1682 against movement relatively to the breast line gripper jaws 990, 992 the housing has an upstanding flange 1692 which is secured by screws 1694 to the slide 1069 which mounts the breast line upper gripper assembly. The shafts 1684 and 1686 are actuated by rotation of the sleeves 1688, 1690, the shafts being held against rotation relatively to the sleeves by cross pins 1696 mounted in their rear end portions and extending through longitudinal slots 1698 in the sleeves. The sleeves are provided respectively with stems 1700 and 1702 mounted in bearings in the rear portion of a bracket 1704 secured to the vertical surface of the arm 1059. The forward portions of the sleeves are mounted in bearings in forwardly extending portions of the bracket 1704. Secured to the rearwardly extending portion of the shaft 1700 is an arm 1706 which extends to the left, as seen in Fig. 61, and is pivotally mounted on a cross pin 1708 mounted in a yoke 1710 which has a universal connection to the upper end portion of a link 1712 (Fig. 60) which is pivotally mounted at its lower extremity to a ball and socket connection 1714 extending upwardly from the horizontal upper end portion 1210 of the vertical slide 1208. The shaft 1702 projects rearwardly from its bearing in the bracket 1704 and has secured thereto a bent arm 1716 which extends to the left from the shaft and has its left end portion slotted for engagement with the cross pin 1708 in the same manner as the arm 1656 illustrated in Fig. 109. The shaft 1684 swings the unit 1680 in a counterclockwise direction, as seen in Fig. 60, to impart overwiping movement to the wiper head at the lower extremity of the unit. The shaft 1686 carries at its forward extremity a short arm 1718 (Fig. 60) which, in conjunction with the arm 1716, on the stem 1702, performs the same function as the lever 1656 illustrated in Fig. 109. Like the lever 1656, the arm 1718 is provided with latch members 1720 which engage a cross pin 1722 (Fig. 60) mounted in the head of the tack driver (not shown). As in the construction illustrated in Fig. 109, the lever 1718 operates to compress a tack driving spring (not shown) and at the end of the overwiping movement the cross pin 1722 moves out of engagement with the latches 1720 and the spring operates to drive a lasting tack which was previously fed into the wiper head either manually or automatically, the tack driving means in the wiper head being the same as in the wiper head 1604, illustrated in Fig. 113.

In the operation of the illustrated machine a lined shoe upper such, for example, as the upper 1724, illustrated in Fig. 2, is positioned between the back line gripper jaws 208 and 210 and located heightwise thereof by engagement with the extension 214 of the jaw 210. Referring to Fig. 12, the upper is located widthwise thereof relatively to the jaw 208 by bringing the notch 236 in the lining into registration with a tooth 240 formed in the jaw 208. The lasting margin of the upper is inserted between the jaws 258 and 266 (Fig. 2) and is positioned

widthwise thereof relatively to the jaws by centering the back line of the upper relatively to the jaw 258. After the shoe upper has been properly located in the back line gripper jaws the treadle 316 (Fig. 1) is depressed to cause the gripper jaws to close. After the jaws have been closed the gripper jaws 208 and 210 are adjusted widthwise of the upper relatively to the jaws 258 and 266 as required to make the angle of the back line of the upper agree with the angle of the back line of the heel form in its inserted position in the upper. The jaws 208 and 210 are adjusted widthwise by movement of the block 219 (Fig. 6) on the surface of the bracket 244, the block 219 being held in adjusted position by the latch plates 232. After the gripper jaws have been closed with the upper properly positioned therein the quarter lining 238 (Fig. 11) is drawn downwardly and toewardly from its position in Fig. 11 into its position illustrated in Fig. 12 in order to provide clearance for the automatic insertion of a molded counter into the heel end portion of the upper.

In the event that the counter conveyor was emptied in the preceding cycle of the machine it is restocked prior to the initiation of the power cycle of the machine by bringing a box of counters into position relatively to the counter conveyor, as shown in Fig. 24, after the retainer plates 568 have been swung into their open position shown in Fig. 24 to admit the box. The operator transfers the counters from the box to the conveyor by bringing two fingers to bear against the flanges of the counters through the openings in the bottom of the box, shown in Fig. 40. This is easily and quickly accomplished by the operator by moving his fingers from top to bottom of the box against the flanges of the counters disengaging them consecutively from the retaining members in the box and moving them rearwardly between the arms 556 which hold them by friction on the counter conveyor with the aid of the retainer plates 568, as shown in Fig. 25.

The counter conveyor having been supplied with suitable counters and the heel end portion of the upper having been positioned in the machine and its quarter lining drawn downwardly and toewardly to provide for the insertion of a counter into the upper, the operator is ready to initiate the main cycle of operations of the machine by the depression of a treadle 1726 (Fig. 1). Referring to Fig. 119 the treadle is connected by a link 1728 to an arm 1730 fixed to a rockshaft 1732 having secured to its rear end portion an arm 1734 which is connected by a bent link 1736 to a slide 1738. The depression of the treadle moves the slide to the left, as seen in Fig. 119, to operate mechanism (not shown) which permits a spring 1740 (Fig. 120) to bring a constantly rotating clutch element 1742 into operating engagement with a clutch element 1744 which rotates with the shaft 156. Three complete rotations of the shaft 156 are required to complete the main cycle of operations of the machine. During each rotation of the shaft a cam 1746 operates to cause a stopping mechanism (not shown) to be positioned to stop the shaft after one complete rotation thereof.

During the first third of the main cycle of the machine the cam 370 (Fig. 19) actuates the counter carrier to transmit a cement treated counter from its draining station into the heel end portion of the upper. In order to provide clearance for the operation of the counter carrier the cam 596 (Fig. 35) imparts upward movement to the counter conveyor assembly at the beginning of the main cycle. During the latter part of the first third of the machine cycle the cam member 476 (Fig. 13) causes the counter spreading pins 452 to spread the wings of the counter into a position facilitating the lining wiping operation which is performed manually during the interval between the first and second thirds of the main cycle. Near the end of the

first third of the cycle the cams 1100 and 1102 (Fig. 59) operate to permit the movement of the breast line gripper assemblies inwardly into an intermediate position determined by the engagement of the pin 1114 (Fig. 67) with the hook 1116. In this position of the breast line grippers the breast line upper gripper jaws are arranged to register generally with the lasting margin of the upper which is then in its outspread position determined by the operation of the cam 476. Also during the first third of the main cycle the cam 1392 (Fig. 85) operates to compress the spring 1390 preparatory to the advancement of the wedge 1368 by the expansion of said spring during the interval between the first and second thirds of the main cycle. Preparatory to the manual operation of the top line pads during the interval between the first and second thirds of the cycle the cam 972 (Fig. 92) operates at the beginning of the cycle to release the latch member 956 (Fig. 88) to the operation of the spring pressed plunger 958 which normally holds the latch member in its operative position shown in Fig. 88. Also during the first third of the machine cycle the two arms 1582 (Fig. 103) on the shaft 178, which hold the feather line pad assemblies retracted when the machine is at rest, move into a position which affords clearance for the advancement of the feather line pad assemblies at a later stage in the machine cycle by the cams 1105 and 1145.

During the interval between the first two thirds of the main cycle of the machine the operator manipulates the quarter lining 238, as shown in Fig. 59, to bring it into a position adjacent to the inner surface of the counter 364 preparatory to the lining wiping operation. The operator then depresses the treadle 200 (Fig. 1) to actuate the lining wipers thereby to bring the heel end portion of the quarter lining into intimate contact with the inner surface of the counter, as shown in Fig. 57, and to bring the bottom margin of the lining into contact with the flange of the counter. Immediately after the wiping operation the wipers are returned to their rest position by gravity when the operator takes his foot off the treadle 200. During the upward movement of the lining wipers the blades 758 (Fig. 72) on the wiper head cooperate with the pins 496 in the counter carrier assembly to guide the bottom margin of the lining into the breast line lining gripper jaws without any further manipulation of the lining by the operator. At the same time the operator manually directs the lasting margin at opposite sides of the upper into the breast line upper gripper jaws. During the course of the lining wiping operation the counter spreading pins 452 (Fig. 51) are returned to their rest positions to permit the counter wings to return to their normal position, shown in Fig. 58, by their inherent resiliency. The inward movement of the spreader pins occurs when the detent 478 (Fig. 13) and the corresponding detent at the opposite side of the machine are retracted by the operation of mechanism hereinbefore described. Approximately concomitantly with the release of the counter wings for inward movement the operation of the lining wiper treadle disengages the hook 1116 (Fig. 67) from the pin 1114 to permit the breast line gripper assemblies to move inwardly to their operating position as the counter wings move inwardly to their normal position. The inward movement of the breast line grippers is terminated by the engagement of the grippers with the wings of the counter. If the machine is operated without any work therein the inward movement of the breast line grippers is terminated by the engagement of the bent pin 1124 (Fig. 68) with the stop pin 1126. It will be understood that a similar mechanism terminates the inward movement of the breast line gripper assembly at the right side of the machine. At an early stage in the return or upward movement of the lining wiper treadle the breast line gripper jaws are closed by the rotation

of the shaft 842 (Fig. 76) which is effected by the engagement of the detent 830 with the plate 838. The rotation of the shaft causes downward movement of the arms 856 and 860 thus releasing the latches which hold the breast line gripper jaws open and permitting the closing of the jaws by spring operated mechanism hereinbefore described. The downward movement of the lining wiper treadle actuates the slide 930 (Fig. 88) and the corresponding slide at the left side of the machine to advance the top line pads 866 and 868 (Fig. 89) thereby to bring the top line portion of the upper into proper relation to the counter just prior to the lining wiping operation. The upward movement of the lining wiper head moves the counter spreader assembly upwardly, as shown in Fig. 52, in order to provide clearance for the advancement of the heel form into the supported upper, the spreader assemblies being retained in elevated position by a latch mechanism hereinbefore described when the lining wiper assembly returns to its rest position.

After the completion of the lining wiping operation an insole such, for example, as the insole 526 illustrated in Fig. 96 is manually positioned relatively to the retracted heel form, whereupon the sliding plate 1234 (Fig. 101) is moved rearwardly to cause the pins 1228 to locate the insole accurately on the heel form and to retain it thereon during the subsequent operation of the machine. After mounting the insole on the heel form the clutch lever 202 (Fig. 93) is operated to initiate the first 180° of the cycle of operations of the heel form 166. During the first 90° of the cycle the heel form assembly is swung from its position indicated in full lines in Fig. 74 into its dotted line position of said figure. At the end of its swinging movement the heel form is spaced toewardly from the heel end portion of the upper, as shown in Fig. 93, and during the second 90° of the cycle the heel form is moved heelwardly into the upper. To provide clearance for the rotary movement of the heel form into its position, shown in Fig. 93, the forepart of the upper is bent downwardly into its position shown in Fig. 79. During the last 20° of the first half of the heel form cycle the shaft 1266 is rotated slightly in a counter-clockwise direction, as seen in Fig. 74, to bring the insole to bear against the abutment screws 524 on the counter carrier thus locating the heel form and the insole thereon heightwise of the supported upper while accurately determining the upward orientation of the insole and the heel form. At the end of 180° of the heel form cycle the heel form comes to rest in proper relation to the upper for the lasting operation which takes place during the last two thirds of the main cycle. During its heelward movement from its position in Fig. 100 to its position illustrated in Fig. 101 the heel form imparts longitudinal tension to the heel portion of the upper from an area at the crest of the back line curvature to the points of engagement of the breast line gripper jaws with the bottom margins of the upper and the lining.

During the rearward movement of the heel form assembly the arm 1248 (Fig. 93) which mounts the heel form, engages the bent lever 1454 (Fig. 79) and moves it rearwardly thereby operating through mechanism hereinbefore described to retract the latch which holds the wedge 1368 in its position illustrated in Fig. 87 thus permitting forward movement of the wedge into engagement with the block 1374. At this time the block is at the limit of its downward movement and, consequently, the forward movement of the wedge upon the retraction of the latch is relatively slight but concomitantly with the upward movement of the lining wiper assembly into heel form supporting position the wedge advances into its position beneath the block 1374 in order to support the wiper assembly positively against downward movement during the wiping and tack driving operations.

The advancement of the wedge following the upward movement to the lining wiper assembly into heel form

supporting position completes the operations preliminary to the operations performed in the last two thirds of the main cycle and, accordingly, after a brief inspection of the work to make certain that the upper is correctly located for the wiping and tack driving operations the operator again depresses the clutch treadle 1726 (Fig. 1) to initiate the second third of the main cycle. During the second third of the cycle the cam 346 (Fig. 10), which applies gripping pressure to the back line gripper jaws, is retracted to permit the jaws to open at a later stage in the main cycle. After a brief dwell to permit the upper engaging pads to engage the upper with sufficient pressure to maintain the position of the counter relatively to the upper the counter carrier is retracted and returned to its counter loading station where it remains until the cam 614 (Fig. 35) operates to load the lowermost counter in the counter conveyor on the counter carrier. Immediately after the loading of the counter on the carrier the cam 596 imparts an upward movement of translation to the counter conveyor assembly to provide clearance for the operation of the counter carrier in the next cycle of the machine. Just before the end of the second third of the main cycle the counter carrier with a dry counter loaded thereon moves downwardly to immerse the counter in the cement bath and the machine comes to rest at the end of the second third of the main cycle with the counter immersed in the cement. During the first part of the second third of the main cycle the cams 1105 and 1145 (Fig. 103) actuate the cam 1137 (Fig. 61) and a similar cam at the right side of the machine to impart toeward movement to the breast line gripper jaws. Such toeward movement of the gripper jaws sets up lines of tension in the upper and the lining extending from the breast line gripper jaws horizontally to the jaws at the junction of the back line of the lasting margin. Such toeward movement also sets up lines of tension extending diagonally across the heel portion of the upper from the breast line gripper jaws to the jaws at the junction at the back line and the top line. The tension thus effected by the toeward movement of the breast line gripper jaws acts in conjunction with the tension effected by the heelward movement of the heel form and the pressure of the upper engaging pads to cause the heel end portions of the upper and the quarter lining to be brought into intimate contact with the entire surface area of the counter with sufficient pressure to insure a satisfactory bonding of the upper and the lining to the counter while the shoe parts are maintained in accurately predetermined relation to each other by the operating instrumentalities of the machine. The actuation of the upper engaging pads by the cams 1105 and 1145 begins in the latter part of the first third of the main cycle and continues through the greater part of the second third of the cycle. During the operation of the breast line gripper jaws the upper engaging pads exert relatively heavy pressure against the back line portion of the upper but only light pressure against the opposite sides of the heel portion of the upper. After the completion of the operation of the breast line grippers the pressure exerted by the upper engaging pads increases until the pads exert sufficient pressure on the upper to maintain the toeward tension imparted to the upper by the operation of the breast line grippers. The breast line gripper jaws are held at the limit of their toeward movement with the upper under tension while the cams 1105 and 1145 continue their operation to complete the actuation of the feather line pads and the top line pads in order to hold the upper in tensioned position on the last after the release of the breast line gripper jaws and during the wiping and tacking operations.

At the end of the second third of the main cycle the machine comes to rest to permit the operator to inspect the work and to determine whether or not to proceed with the wiping and tacking operations. If conditions are favorable the operator again depresses the clutch treadle to initiate the final third of the main cycle. At an early

stage in the last third of the cycle the cam 324 (Fig. 10) operates to open the back line gripper jaws preparatory to the wiping and tacking operations. The cam 370 (Fig. 19) operates at the beginning of the last third to lift the counter which was immersed during the second third of the cycle into its draining station in which it remains during the remainder of the main cycle and thereafter until the next operation of the machine when the cement treated counter is inserted into a shoe upper. During the first part of the last third of the cycle the cam 1194 operates through mechanism hereinbefore described to open the back line gripper jaws to their latched position. Further operation of the cam 1194 (Fig. 10) actuates the back line wipers and the breast line wipers to wipe the lasting margin of the upper in over the insole on the heel form. The operation of the cam 1194 also compresses the tack driving spring and at the end of the wiping operations the tack drivers are automatically released to permit the springs to actuate the drivers to drive the tacks through the overlasted margin of the upper, the flange of the counter, the margin of the quarter lining, and the margin of the insole and to clench the tacks against the surface of the metal heel form. During the latter part of the machine cycle the wiper and tacker units are returned to their respective rest positions by a spring 1748 (Fig. 34). During the final third of the cycle the pressure of the cam 1105 and its companion cam 1145 on the feather line pads and the top line pads is relieved and the pads are returned to their respective rest positions. Also during the final third the cam 1392 (Fig. 85) withdraws the wedge 1368 to permit the lining wiper assembly to be moved downwardly into its rest position. After the completion of the wiping and tacking operations the cam 1100 (Fig. 59) and its companion cam 1102 swing the breast line gripper assemblies outwardly into their respective retracted positions illustrated in Fig. 59. Concomitantly with the retraction of the breast line gripper assemblies the cam 1344 (Fig. 75) initiates the operation of the clutch 1342 (Fig. 79) to start the last half of the cycle of operations of the cams 1284 and 1298 which return the heel form to its rest position. Preparatory to the return movement of the heel form to its rest position the back line gripper jaw 208 is moved downwardly into its position illustrated in Fig. 64 to provide clearance for the toward movement of the heel end portion of the upper incidental to the return movement of the heel form. The downward movement of the jaw 208 occurs concomitantly with the opening movement of the back line gripper jaws, being effected by the expansion of the spring 227 upon the retraction of the latch 233 by the downward movement of the cam member 245. During the interval between the end of the cycle and the introduction into the machine of the next upper to be operated upon, the gripper jaw 208 is manually returned to its operative position. During the latter part of the main cycle the two arms 1582 (Fig. 103) fixed to the shaft 178 advance the slides 1590 to retract the feather line pads and at the same time the cam 972 (Fig. 92) operates to disengage the latch member 956 (Fig. 88) and its companion latch member from the arm 920 and a like arm at the opposite side of the machine to permit the top line pads to return by gravity to their respective rest positions. At the beginning of the following cycle cam 972 operates to swing the arm 982 (Fig. 88) upwardly to permit the spring pressed plunger 958 to return the latch members to their respective operative positions.

Upon the completion of the main cycle of the machine the operator draws the sliding cam plate 1234 (Fig. 100) forwardly to retract the two pins 1228 in order to permit the assembled upper and insole to be removed from the heel form 166.

Having thus described our invention, what we claim as new and desire to secure by Letters Patent of the United States is:

1. In a shoe machine, a counter carrier, means for

- operating the carrier to insert a counter thereon into a shoe upper supported in the machine, an insole carrier, means for gripping the bottom margin at opposite sides of the shoe upper in the region of the heel breast line, 5 means for effecting relative movement of the grippers and the insole carrier lengthwise of the shoe upper thereby to tension the upper lengthwise, and means for fastening the upper and the counter to the insole while the upper is under tension.
- 10 2. In a shoe machine, a counter carrier, means for operating the carrier to insert a counter thereon into a shoe upper supported in the machine, an insole carrier, means for gripping the bottom margin at opposite sides of the shoe upper in the region of the heel breast line, 15 means for moving the insole carrier heelwardly while the upper is held by the gripping means thereby to tension the heel portion of the upper lengthwise thereof, and means for fastening together the upper, the counter and the insole while the heel portion of the upper is under tension.
- 20 3. In a shoe machine, means for supporting an assembly comprising a shoe upper and a heel stiffener, an insole carrier, means for operating the insole carrier to insert an insole thereon into the assembly, means for fastening the assembly to the insole in the region of the back line 25 of the upper, and means for fastening the assembly to the insole at opposite ends of the breast line.
4. In a shoe machine, means for supporting an assembly comprising a shoe upper and a heel stiffener, an insole carrier, means for operating the insole carrier to insert an insole thereon into the assembly, means for tensioning the heel end portion of the upper lengthwise, means for fastening the assembly to the insole in the region of the back line of the upper, and means for fastening the assembly to the insole at opposite ends of the breast line.
- 35 5. In a shoe machine, means for supporting an assembly comprising a shoe upper and a heel stiffener, an insole carrier, means for operating the insole carrier to insert an insole thereon into the assembly, means operating locally at the back line portion of the upper for wiping the bottom margin of the upper in over the margin of the insole, means operating locally at opposite ends of the breast line to wipe the bottom margin of the upper in over the margin of the insole, means for fastening the bottom margin of the upper to the insole in the region 40 of the back line, and means for fastening the bottom margin of the upper to the insole at opposite ends of the breast line.
6. In a shoe machine, means for supporting a lined shoe upper, a carrier for a flanged counter, means for operating the counter carrier to insert a counter thereon into a lined shoe upper supported in the machine, means for wiping the heel end portion of the shoe lining into intimate contact with the body portion and the flange of the counter, an insole carrier, means for operating the 50 insole carrier to insert an insole thereon into the supported upper, means for wiping the bottom margin of the upper in over the flange of the counter, and means for fastening together the overwiped margin of the upper, the flange of the counter, the bottom margin of the lining and the margin of the insole.
7. In a shoe machine, means for supporting a lined shoe upper comprising a gripper constructed and arranged to engage the upper and the lining at the junction of the back line and the top line and a gripper constructed and 55 arranged to engage the upper only at the junction of the back line and the lasting margin, means for inserting a counter into the heel end portion of a supported upper, means for wiping the heel end portion of the lining into intimate contact with the counter, an insole carrier, means for operating the insole carrier to insert an insole thereon into the heel end portion of the supported upper, means for wiping the lasting margin of the upper in over the margin of the insole, and means for fastening the lasting margin to the insole.
- 60 8. In a shoe machine, means for supporting a lined

shoe upper comprising a gripper constructed and arranged to engage the upper and the lining at the junction of the back line and the top line and a gripper constructed and arranged to engage the upper only at the junction of the back line and the lasting margin, means for inserting a flanged counter between the upper and the lining at the heel end portion of a supported upper, means for wiping the heel end portion of the lining into intimate contact with the body portion and the flange of the counter, an insole carrier, means for operating the insole carrier to insert an insole thereon into the heel end portion of the supported upper, means for holding the insole carrier against movement heightwise of the upper, means for wiping the lasting margin of the upper in over the flange of the counter, and means for fastening the overwiped margin of the upper, the flange of the counter and the bottom margin of the lining to the margin of the insole.

9. In a shoe machine, means for supporting a shoe upper by its back line portion, means for gripping the upper at opposite ends of the breast line portion, an insole carrier having incorporated therein a shape corresponding to the heel end portion of a shoe upper, and means for operating the insole carrier to insert an insole into a shoe upper supported in the machine and to apply molding pressure to the inner surface of the back line portion of the upper.

10. In a shoe machine, means for supporting a shoe upper by its back line portion, breast line grippers constructed and arranged to engage the bottom margin of the upper at opposite ends of the breast line, an insole carrier having incorporated therein a shape corresponding to the heel end portion of a shoe upper, and power operated means for advancing the insole carrier to cause it to shape the heel end portion of the upper by engagement with the inner surface thereof and to position the insole thereon for assembly with the supported shoe upper.

11. In a shoe machine, means for supporting a shoe upper by its back line portion, breast line grippers constructed and arranged to engage the bottom margin of the upper at opposite ends of the breast line, an insole carrier having incorporated therein a shape corresponding to the heel end portion of a shoe upper, power operated means for advancing the insole carrier to cause it to shape the heel end portion of the upper by engagement with the inner surface thereof and to position the insole thereon for assembly with the supported shoe upper, means for holding the insole carrier against movement heightwise of the upper, and means for fastening the bottom margin of the upper to the insole.

12. In a shoe machine, means for supporting a shoe upper by its back line portion, grippers constructed and arranged to engage the bottom margin of the upper at opposite ends of the breast line, an insole carrier having incorporated therein a shape corresponding to the heel end portion of a shoe upper, means for urging the grippers toewards to apply lengthwise tension to the upper, and means for operating on the insole carrier to insert an insole into the upper and to apply shaping pressure to the inner surface of the back line portion of the upper.

13. In a machine for inserting a counter into a shoe upper, the combination with means for supporting a shoe upper, of a carrier for inserting a counter into the supported upper, a conveyor constructed and arranged to mount a plurality of counters, means for operating the conveyor to advance a counter thereon to a leading station, means for further operating the conveyor to advance the counter in the leading station to a loading station relatively to the carrier thereby to permit the transfer of the counter from the conveyor to the carrier.

14. In a machine for inserting a counter into a shoe upper, means for supporting a shoe upper, a carrier for inserting a counter into the supported upper, a conveyor constructed to mount a plurality of counters, means for operating the conveyor step by step thereby to advance

the counters one by one into a leading station in the conveyor, and means for actuating the conveyor to advance the counter in the leading station to a loading station relatively to the carrier thereby to permit the transfer of the counter to the carrier.

15. In a machine for inserting a counter into a shoe upper, means for supporting a shoe upper, a carrier for inserting a counter into the supported upper, a conveyor constructed to mount a plurality of counters, said conveyor comprising a member constructed to mount a plurality of counters, a carriage in which the member is mounted for movement step by step first to advance the counters one by one into a leading station relatively to the carriage, and means for advancing the carriage to transfer a counter in the leading station to a loading station relatively to the carrier.

16. In a shoe machine, a carrier for inserting a counter into a supported upper, a conveyor constructed and arranged to mount a plurality of counters, means for actuating the conveyor to transfer a counter thereon to the carrier, an immersion vessel, and means for actuating the carrier first to immerse the counter thereon in fluid in the vessel and thereafter to insert the treated counter into the supported upper.

17. In a shoe machine, means for supporting a shoe upper, a counter carrier, a conveyor constructed and arranged to mount a plurality of counters, means for operating the conveyor to transfer a counter thereon to the carrier, and means for actuating the carrier to move the counter to a cement applying station and thereafter to advance the cement treated counter into the supported upper.

18. In a shoe machine, means for supporting a shoe upper for the reception of a counter, a counter carrier mounted for movement in a generally arcuate path, and means for actuating the carrier to advance a counter thereon into a coating station at one end of the arcuate path of movement of the carrier and into the supported upper at the opposite end of the arcuate path of movement of the carrier.

19. In a shoe machine, means for supporting a shoe upper for the reception of a counter, a counter carrier, means for locating the carrier in a loading station for the reception of a counter, the carrier being movable manually from the loading station to a coating station, and power operated means for operating the carrier to carry a coated counter thereon to the supported upper.

20. In a shoe machine, a carrier for inserting a counter into a supported upper, said carrier comprising a counter holder and a member on which the holder is mounted for counter-orienting movement, means for operating the carrier between a counter coating station and a counter inserting station, and means operating during movement of the carrier in one direction to move the holder relatively to the member thereby to determine the orientation of the counter in the coating station.

21. In a shoe machine, a carrier for inserting a counter into a supported upper, said carrier comprising a counter holder and a member on which the holder is mounted for counter-orienting movement, means operating during movement of the carrier in one direction to move the holder relatively to the member thereby to determine the orientation of the counter in a coating station and operating during movement of the carrier in the opposite direction to move the holder relatively to the member thereby to determine the orientation of the counter in the inserting station.

22. In a shoe machine, a carrier for inserting a counter into a supported upper, said carrier comprising a counter holder and a member on which the holder is mounted for counter-orienting movement, means for operating the carrier between a counter coating station and a counter inserting station, and a fixed cam means effective during movement of the counter in one direction to cause a movement of the holder relatively to the member to determine

the orientation of the counter in the coating station and effective during movement of the carrier in the opposite direction to cause movement of the holder relatively to the member to determine the orientation of the counter in the inserting station.

23. In a shoe machine, a carrier for inserting a counter into a supported upper, said carrier comprising a counter holder and a member on which the holder is mounted for counter-orienting movement, a conveyor constructed and arranged to mount a plurality of counters, means for actuating the conveyor to transfer a counter thereon to the carrier, means for operating the carrier between a counter coating station and a counter inserting station, and a fixed cam means effective during movement of the counter in one direction to cause a movement of the holder relatively to the member thereby to determine the orientation of the counter in the coating station and effective during movement of the carrier in the opposite direction to cause movement of the holder relatively to the member thereby to determine the orientation of the counter in the inserting station.

24. In a shoe machine, means for supporting a shoe upper for the reception of a counter, a counter carrier, means for operating the carrier first to advance the counter into a coating station and thereafter to advance the counter into the supported upper, and adjustable means for determining the position of the counter heightwise thereof in the supported upper.

25. In a shoe machine, means for supporting a shoe upper for the reception of a counter, a counter carrier, a cam for operating the carrier first to advance the counter into a coating station and thereafter to advance the coated counter into the supported upper, and adjustable means incorporated in the cam for determining a position of the counter heightwise thereof in the supported upper.

26. In a shoe machine, a counter carrier and a conveyor for loading a winged counter on the carrier, said conveyor comprising a carriage, a carrier chain mounted in the carriage, gripping means incorporated in the chain and constructed and arranged to engage the top margin of the counter in the region of the back line, and means incorporated in the carriage for positioning the wings of the counter heightwise thereof.

27. In a shoe machine, a counter carrier and a conveyor for mounting a winged counter on the carrier, said conveyor being characterized by a chain, a member on the chain constructed and arranged to engage the inner surface of the top margin of the counter in the region of the back line and a pair of members on the chain constructed and arranged to engage the outer surface of the top margin of the counter at opposite sides of the back line, a carriage in which the chain is mounted, and means on the carriage for positioning the wings of the counter heightwise thereof.

28. In a shoe machine, means for supporting a shoe upper for the reception of a winged counter, means for transferring a winged counter from a loading station to the supported upper and a conveyor for mounting a counter on the transfer means, said conveyor comprising a carriage, a carrier mounted in the carriage for movement relatively thereto, gripping means incorporated in the carrier and constructed and arranged to engage the top margin of the counter in the region of the back line, and means incorporated in the carriage for positioning the wings of the counter heightwise thereof.

29. In a shoe machine, means for supporting a shoe upper for the reception of a winged counter, means for transferring a winged counter from a loading station to the supported upper and a conveyor for loading a counter on the transfer means, said conveyor being characterized by a carrier, a carriage in which the carrier is mounted for movement relatively thereto, a member on the carrier constructed and arranged to engage the inner surface of the top margin of the counter in the region of the back line, a pair of members mounted on the carrier and con-

structed and arranged to engage the outer surface of the top margin of the counter at opposite sides of the back line, and means on the carriage for positioning the wings of the counter heightwise thereof.

5 30. In a shoe machine, means for supporting a shoe upper for the reception of a winged counter, means for transferring a winged counter from a loading station to the supported upper and a conveyor for loading a counter on the transfer means, said conveyor being characterized by a carrier, a carriage in which the carrier is mounted for movement relatively thereto, a member on the carrier constructed and arranged to engage the inner surface of the top margin of the counter in the region of the back line, a pair of members mounted on the carrier and constructed and arranged to engage the outer surface of the top margin of the counter at opposite sides of the back line, and a pair of guide rails mounted on the carriage and arranged to position the wings of the counter heightwise thereof.

10 31. In a shoe machine, a counter inserter and a conveyor comprising a counter carrier and a carriage in which the carrier is mounted for movement relatively thereto, means for advancing the carriage relatively to the inserter, and means for advancing the carrier relatively to the carriage.

15 32. In a shoe machine, a counter inserter and a conveyor for loading counters on the inserter, said conveyor comprising a carriage and a counter carrier mounted in the carriage for movement relatively thereto, means for advancing the carriage relatively to the inserter, and means for effecting relative movement of the inserter and the carrier thereby to transfer a counter from the carrier to the inserter.

20 33. In a shoe machine, a counter inserter and a conveyor for loading counters on the inserter, said conveyor comprising a carriage and a carrier mounted in the carriage for movement relatively thereto, said carrier being constructed and arranged to mount a plurality of counters, means for advancing the carriage relatively to the inserter, and means for advancing the carrier step by step relatively to the carriage.

25 34. In a shoe machine, a counter inserter and a conveyor for loading counters on the inserter, said conveyor comprising a carriage and a carrier in the form of an endless chain mounted in the carriage for movement relatively thereto, said carrier being constructed and arranged to mount a plurality of counters, means for advancing the carriage relatively to the inserter, and means for advancing the carrier step by step relatively to the carriage.

30 35. In a shoe machine, a counter inserter and a conveyor for loading counters on the inserter, said conveyor comprising a carriage and a carrier in the form of an endless chain mounted in the carriage for movement relatively thereto, said carrier being constructed and arranged to mount a plurality of counters, means for advancing the carriage relatively to the inserter, and a power-operated pawl and ratchet mechanism for advancing the carrier step by step relatively to the carriage.

35 36. In a shoe machine, a counter inserter and a conveyor for loading counters on the inserter, said conveyor comprising a carriage and a carrier in the form of an endless chain mounted in the carriage for movement relatively thereto, said carrier being constructed and arranged to mount a plurality of counters in uniformly spaced relation thereon, means for advancing the carriage relatively to the inserter, and means for indexing the carrier relatively to the carriage by increments corresponding to the distance between adjacent counters on the carrier.

40 37. In a shoe machine, a counter inserter and a conveyor for loading counters on the inserter, said conveyor comprising a counter carrier and a carriage on which the carrier is mounted for movement relatively thereto, and means in the carriage for locating relatively to the carrier a box containing counters to be mounted on the carrier.

45 38. In a shoe machine, a carrier for mounting a plu-

rality of counters and for loading the counters one by one on a transfer member, gripping means incorporated in the carrier and constructed and arranged to engage the counters in the region of the back line and a pair of rails for positioning opposite side portions of the counters heightwise thereof, said rails being retractable in order to admit a box of counters into position for the transfer of the counters from the box to the carrier.

39. In a shoe machine, means for supporting a shoe upper off the last, an insole carrier, means for operating the carrier to insert an insole into the supported upper, means for moving the carrier heelwardly, and means for moving the carrier heightwise of the upper into predetermined relation thereto.

40. In a shoe machine, means for supporting a shoe upper off the last, an insole carrier, means for operating the carrier to insert an insole into the supported upper, means for moving the carrier heelwardly, abutment means for determining a position of the carrier heightwise of the upper, and means for moving the carrier heightwise of the upper to bring an insole thereon into engagement with the abutment means.

41. In a shoe machine, means for supporting a shoe upper off the last, a carrier for inserting a loose insole into the supported upper, means for positioning and retaining such an insole on the carrier comprising pins extending convergently from the carrier through apertures in the insole, and means for moving the carrier heightwise of the upper into predetermined relation thereto.

42. In a shoe machine, means for supporting a shoe upper, a carrier for inserting a loose insole into the supported upper, means for positioning and retaining such an insole on the carrier comprising pins extending convergently from the carrier through apertures in the insole, means for moving the carrier heightwise of the upper into predetermined relation thereto, and means for retracting the pins to permit the removal of the insole from the carrier.

43. In a shoe machine, a heel form characterized by a plurality of pins projecting from its sole face for locating an insole thereon, and cam means mounted in the heel form for advancing the pins into projecting position and for retracting them into the heel form.

44. In a shoe machine, a heel form characterized by a plurality of pins constructed and arranged to project convergently from the sole face of the form through apertures in an insole mounted on the sole face, and a cam member mounted in the heel form and operable to advance the pins into projecting position and to retract the pins into the heel form.

45. In a shoe machine, means for supporting a shoe upper off the last, a heel form characterized by a plurality of pins for positioning an insole thereon, means including a shaft for mounting the heel form, means for moving the shaft endwise thereby to advance the form heelwardly into a supported upper, means for rotating the shaft in one direction prior to the endwise movement of the shaft thereby to insert the heel form into the supported upper and in the opposite direction after the endwise movement of the shaft thereby to move the heel form generally heightwise of the supported upper into predetermined relation thereto.

46. In a shoe machine, a heel form characterized by a plurality of pins constructed and arranged to project from the sole face of the form through apertures in an insole mounted thereon, a member on which the heel form is mounted for self-orientation by engagement with abutment means, and means mounted in the heel form and

operable to advance the pins into projecting position and to retract the pins into the heel form.

47. In a shoe machine, means for supporting a shoe upper at opposite ends of the back line, breast line grippers constructed and arranged to engage the bottom margin of the upper, a heel form, means for advancing the heel form into contact with a limited area of the back line portion of the upper and for further advancing the heel form to shape the back line portion of the upper, and means for yieldingly holding the breast line grippers against heelward movement in response to the movement of the heel form thereby to cause the heel portion of the upper to be tensioned on lines extending from the breast line grippers to the point of contact of the heel form with the back line portion of the upper.

48. In a shoe machine, means for supporting a shoe upper at opposite ends of the back line, breast line grippers constructed and arranged to engage the bottom margin of the upper, a heel form, means for advancing the heel form into contact with a limited area of the back line portion of the upper and for further advancing the heel form to shape the back line portion of the upper, means for yieldingly holding the breast line grippers against heelward movement in response to the movement of the heel form thereby to cause the heel portion of the upper to be tensioned on lines extending from the breast line grippers to the point of contact of the heel form with the back line portion of the upper, and means for moving the breast line grippers toewards to further tension the heel end portion of the upper.

49. In a shoe machine, grippers constructed and arranged to engage a shoe upper at opposite ends of the back line, means for moving the grippers from each other thereby to tension the back line portion of the upper heightwise thereof, breast line grippers constructed and arranged to engage the bottom margin of the upper, a form having incorporated therein the general shape of the heel end portion of a shoe, means for advancing the form into contact with a limited area of the back line portion of the upper and for further advancing the form to shape the back line portion of the upper, and means for yieldingly holding the breast line grippers against heelward movement in response to the movement of the form thereby to cause the heel portion of the upper to be tensioned on lines extending from the breast line grippers to the point of contact of the heel form with the back line portion of the upper.
